CAN PACKAGING MACHINE

William A. Ringler, Wayne, Pa., assignor to The Gardner Board & Carton Co., Middletown, Ohio, a corporation of Ohio

Application January 14, 1954, Serial No. 404,018

49 Claims. (Cl. 53—40)

This invention relates to can packaging apparatus designed to apply flat wrapper blanks in embracing relation to successive can groups and to secure portions of the enwrapped blank together to provide completed can packages for distribution and sale.

Various canned products such as beverages, foods and the like can be advantageously merchandized in groups of three or more cans when enclosed within a suitable carton or wrapper carrier. Since the cost of the cartons or wrappers, as well as the cost of packaging the cans therein, must be added to the price at which the completed can packages are sold, thought and attention is constantly being directed to ways and means for reducing the overall packaging costs, including the cost of producing the can enclosing cartons or wrappers as well as the cost of performing the packaging operation.

This invention is directed to the provision of an improved packaging machine designed to operate on simplified wrapper blanks which can be produced at low cost and substantially without waste of sheet material. This improved can packaging apparatus is substantially automatic in operation and may be operated at high production speeds. The apparatus is equipped with blank feeding mechanism for depositing successive blanks onto a continuously traveling conveyor which is composed of a series of hingedly connected blank supporting platforms having means associated therewith for unfolding the blank side panels and infolding and securing the top panel sections together and in encasing relation to can groups during continuous travel thereof on the conveyor. This apparatus is further equipped with can feeding and loading mechanism designed to deliver and deposit a predetermined number of cans in position on the traveling wrapper blank as supported on the conveyor platforms. The apparatus also includes means for manipulating parts of the can wrapping devices to thereby enwrap the can groups in the wrapper blanks during continuous and uninterrupted travel thereof. This improved apparatus is also provided with means and devices for firmly securing the enwrapped blanks in tubular form to thereby tightly encase and lock the can groups therein.

The can packaging apparatus of this invention is designed to apply various different shapes and forms of wrapper blanks to can groups during the continuous travel thereof. Where the wrapper blank is provided with paired handle sections by means of which the can package is carried, it is preferable to secure the paired handle sections together as by staples. Where the wrapper blank is shaped to provide overlapped top panel sections, having spaced finger insertion holes therein by means of which the completed can package may be carried, the overlapped top panel sections may be advantageously glued together. The can packaging apparatus of this invention may be provided with suitable stapling devices for applying two or more staples to the paired handle sections of the can enclosing wrapper blank, or alternatively, the apparatus may be provided with adhesive applying means to secure the

2

overlapped top panel sections of the wrapper blank firmly together.

An object of this invention is to provide an improved can packaging apparatus operative to automatically enwrap and secure various forms of wrapper blanks to can groups in continuous production and at high production speeds.

Another object of this invention is to provide an automatically operative can packaging apparatus having mechanism for depositing wrapper forming blanks in uniform spaced relation on a continuously traveled conveyor, mechanism for grouping and depositing can groups on the continuously traveling blanks, mechanism for tightly enwrapping the blanks around the can groups during continuous travel thereof, mechanism for firmly securing the blanks in tightly wrapped relation around the can groups to provide completed can packages, and mechanism for successively discharging the completed can packages from the apparatus at high production speeds.

A further object of this invention is to provide an improved can grouping and loading mechanism adapted to operate in association with a can filling machine and which is designed to receive the cans from either one or two can conveyor lines, to group the cans in closely nested relationship, and to deposit the can groups in accurately registered position on the bottom panels of rapidly advancing can wrapping blanks.

A further object of this invention is to provide an improved mechanism for enclosing wrapper blanks tightly and snugly around can groups during continuous and uninterrupted travel thereof at high speed.

Other objects and advantages of this invention will become apparent as the disclosure proceeds.

Although the characteristic features of this invention will be particularly pointed out in the claims, the invention itself, and the manner in which it may be carried out, may be better understood by referring to the following description taken in connection with the accompanying drawings forming a part hereof, in which

Fig. 1 is a diagrammatic plan view of the can packaging apparatus of this invention which generally illustrates the path of travel of the cans and the wrapper blanks into packaging position, and also the travel of the partly formed and completed can packages through the apparatus.

Fig. 2 is a diagrammatic side elevation of the transporting conveyor, with the associated blank feeding mechanism and can feeding mechanism shown in their relative positions along the conveyor, this view also showing a side elevation of the can packages in process of formation and the manner in which the completed can packages are discharged from the apparatus.

Fig. 3 is a plan view of one form of can wrapper blank which may be used for application to a group of six cans by the apparatus of this invention.

Fig. 4 is a perspective view of the completed can package formed from the blank shown in Fig. 3 and as the same appears when applied to the can group by the apparatus of this invention.

Fig. 5 is a modified form of can blank designed to be tightly wrapped and secured around a can group by the can packaging apparatus of this invention.

Fig. 6 is a perspective view of the completed can package formed from the blank shown in Fig. 5 as wrapped around a can group.

Fig. 7 is a side elevation of the can packaging apparatus showing certain details of the framework structure which may be employed to support the conveyor and the various operating mechanisms associated with the apparatus.

Fig. 8 is a top plan view of the can packaging apparatus showing the framework structure and certain of the operating mechanisms associated therewith in further detail.

Fig. 9 is a transverse section showing further details of the framework structure, the can feeding mechanism and parts of the conveyor guides as the same would appear when viewed along line 9—9 of Fig. 7.

Fig. 10 is a fragmentary cross section taken longitudinally of the apparatus as the same would appear when viewed along line 10—10 of Fig. 1, this view showing further details of the transporting conveyor, the conveyor supporting sprocket at the head end of the machine, and the manner in which the can wrapper blanks may be deposited on the packaging platforms which form part of the conveyor.

Fig. 11 is a transverse cross section of the apparatus as the same would appear when viewed along line 11—11 of Fig. 10, this view showing further details of the transporting conveyor and associated can wrapping buckets, the conveyor supporting sprocket at the head end of the apparatus, and certain details of the blank feeding mechanism which may be employed.

Fig. 12 is a transverse cross section of the apparatus as the same would appear when viewed along line 12—12 of Fig. 1, this view illustrating further details of the can feeding rotors and drives therefor, as well as the relative position of the side wings of the can wrapping platforms when in process of can loading.

Fig. 13 is a top plan view of a portion of the can packaging apparatus which further illustrates the manner in which the can group is loaded on to the bottom panel of the wrapper blank and the guide devices employed for erecting the side wings of the packaging platforms into can wrapping position.

Fig. 14 is a transverse section of the apparatus as the same would appear when viewed along line 14—14 of Fig. 13, this view showing the side wings of the can wrapping platform in process of erection to enwrap the side panels of the can blank against the sides of the can group.

Fig. 15 is another transverse section of the apparatus when viewed along line 15—15 of Fig. 13 and at a more advanced stage in the wrapping operation, this view showing the side wings of the can wrapping platform fully erected to tightly enwrap the side panels and the top panel sections of the wrapper blank against the side walls and the top end of the can group.

Fig. 16 is an end elevation of the can wrapping platform showing the side wings thereof erected in full lines, the outline of the side wings also being shown in their extended position for receiving the initially flat can blank.

Fig. 17 is a side elevation of the can wrapping platform as the same would appear when the side wings are in fully erected position, the relative position of the wings of the preceding and following can wrapping platforms being shown in dot and dash lines.

Fig. 18 is a bottom plan view of the can wrapping platform which illustrates further structural details thereof.

Fig. 19 is a fragmentary top plan view of the can feeding rotors and associated can guide tracks which merge the two can rows into adjacent position for packaging into can groups.

Fig. 20 is another top plan view of the merging sections of the can guide tracks which further illustrates the manner in which the two can rows are merged together to provide compact can groups.

Fig. 21 is a fragmentary transverse section taken along line 21—21 of Fig. 20 which further illustrates the manner in which the can tracks guide the two rows of cans onto the bottom panel of the wrapper blank as supported on the bottom platform of the can wrapping bucket.

Fig. 22 is a further cross section of the can loading sections of the paired can guiding tracks as the same would appear when viewed along line 22—22 of Fig. 20, this view showing a pair of cans in process of ejection from the paired can tracks and in position on the bottom panel of the wrapper blank as supported on the bottom platform of the can wrapping bucket.

Fig. 23 is a further fragmentary top view of the can loading sections of the can guiding tracks, this view showing two pairs of cans as they would appear when ejected from the guiding tracks and positioned on the bottom panel of the wrapper blank as supported on the bottom platform of the can wrapping bucket.

Fig. 24 is a side elevation of a portion of the can packaging machine of this invention which is alternatively equipped with a glue applicator and a pressure applying device for gluing and sealing the top panel sections of the can packages as formed from the wrapper blank shown in Fig. 5.

Fig. 25 is a top plan view of a portion of the alternative form of can packaging machine of Fig. 24, this view showing further details of the glue applicator which operates to apply parallel strips of adhesive to one of the top panel sections of the blank shown in Fig. 5 and the pressure device which operates to apply bonding pressure to the overlapped top panel sections to thereby produce the completed can package as shown in Fig. 6.

Fig. 26 is a transverse section of the modified apparatus shown in Figs. 24 and 25 as viewed along line 26—26 of Fig. 25, this view showing further details of the glue applicator and the manner in which parallel strips of adhesive are applied to one of the top panel sections of the blank as supported in the expanded can wrapping bucket during continuous travel thereof;

Fig. 27 is another transverse section of the modified apparatus as the same would appear when viewed along line 27—27 of Fig. 25, this view showing further details of the device employed to apply bonding pressure to the overlapped top panel sections of the can package as contained within the continuous traveling can wrapping bucket; and

Fig. 28 is a diagrammatic view of the drive connections which may be employed to drive the various mechanism associated with this can packaging apparatus.

To exemplify the various forms of wrapper blanks on which the apparatus of this invention is adapted to operate, two forms of can wrapper blanks are shown in Figs. 3 and 5 for purposes of illustration. The can wrapper blanks are preferably formed from relatively tough and strong paperboard or fiberboard stock sheets which caliper from 20 to 40 thousandths of an inch in thickness, but it will be appreciated that various other fibrous, plastic, or metallic sheet materials may be employed to provide the wrapper blanks to be packaged on the apparatus of this invention. The wrapper blanks are sized to snugly contain and support the can group when arranged in two closely adjacent rows, each row comprising two, three, four, five, six or more cans as desired. Although the apparatus may be constructed in accordance with this invention to package can groups comprising a single or a double row of cans of any desired number, for convenience in description the can packaging machine as illustrated in the accompanying drawings has been sized to package can groups of six cans each.

The can wrapper blanks A and A' as shown in Figs. 3 and 5, both present a bottom panel *a* sized to snugly support a group of six cans. A pair of side panels *b* are foldably connected to the opposite side edges of the bottom panel, the height of the side panels *b* being closely equal to the height of the cans *C* to be packaged in the wrapper blank. An infolding top panel section *d* is connected to each of the side panels *b*. A series of spaced cuts *e*, which may be either arcuate or U shaped, are located along the line of juncture between the side panels *b* and the bottom panel *a*, and also at the line of juncture between the side panels *b* and the top panel sections *d*. Thus, when the blanks are shaped into package form as shown in Figs. 4 and 6, relatively narrow can chime receiving slits *e'* are formed along the lower and upper edges of the side panels *b* to receive the can chimes *c'*

and thereby lock the individual cans of the can group firmly within the wrapper blank.

Each of the top panel sections *d* of the blank shown in Fig. 3 has a width which closely approximates the can diameter, and a handle section *f* is foldably connected along fold line *g* to each top panel section *d*. When the can group is snugly packaged within the wrapper blank as shown in Fig. 4, the paired handle sections *f* will overlap, and may thus be secured together as by spaced staples *s* placed adjacent the bend lines *g* of the handle sections. The paired handle sections *f* may also be provided with aligned holes *h* through which the fingers may be inserted for carrying purposes.

The blank A' shown in Fig. 5 is provided with a pair of infolding top panel sections *d* which are of sufficient width to provide a substantial overlap when infolded over the upper end of the can group. The overlapped top panel sections *d* are preferably secured together by two parallel strips of adhesive *i* which may be applied to one or both top panel sections *d* immediately prior to the upfolding of the side panels. Each of the top panel sections *d* of the blank A' are also provided with a pair of finger insertion holes *j* which fall into aligned registry when the top panel sections *d* are infolded and adhesively secured together to provide the complete can package as shown in Fig. 6.

As shown in the accompanying drawings, the can packaging apparatus of this invention generally comprises a continuous transportation conveyor 10 composed of a series of can wrapping buckets 30 hinged together at the ends thereof and thus provide the connected links of the conveyor. Each can wrapping bucket 30 includes a pair of foldable side wings 34 which are supported in outswung position by an arrangement of guide tracks during the traveling interval when the bucket remains unloaded and when it receives the can blank and the can group. The apparatus also includes blank feeding mechanism 70 for depositing the initially flat wrapper blanks, such as the blank A or A', in registered position within the traveling can wrapping buckets 30 and while the side wings thereof are extended. The apparatus additionally includes can driving, can grouping and can depositing mechanism 90 operative to drive and direct two rows of cans into parallel relation, to thereupon closely nest the cans into can groups, and to deposit each can group in accurately registered position on the bottom panel of the wrapper blank as supported upon the bottom platform of the expanded can wrapping bucket during travel thereof.

The apparatus is also equipped with cooperating devices associated with the framework structure and the side wings of the buckets for upswinging the bucket side wings to thereby upfold the side panels *b* of the wrapper blank into snug hugging relation against the sides of the can group. The side wings of each bucket 30 are equipped with in-turned end flanges 36 which maintain the can group in accurate position, and with in-turned top flanges 37 which operate to infold the top panel sections *d* of the wrapper blank in close overlying relation across the upper end of the associated can group, which operation is automatically effected when the side wings of the bucket have been fully erected.

Where wrapper blanks in the form shown in Fig. 3 are employed, this can packaging apparatus is equipped with devices 121 for upturning the paired handle sections *f* of the blank into overlapped relation. Suitable stapling mechanism 128 is also provided which is operative to apply spaced staples *s* to the upfolded handle sections adjacent the crotch lines *g* thereof while the overlapped handle sections are firmly held in overlapped relationship.

Where wrapper blanks formed as shown in Fig. 5 are employed, this apparatus is alternatively equipped with a glue applicator device 130 as shown more particularly

in Figs. 25 and 26 which operates to apply two parallel strips of adhesive *i* longitudinally across one of the top panel sections *d* during continuous travel of the blanks as supported in extended position on the expanded can wrapping buckets. In the alternative form of the apparatus as shown in Figs. 25 to 28 inclusive, the stapling mechanism may be rendered inoperative or eliminated, and a pressure applying device 140 substituted which operates to apply bonding pressure in the overlapped top panel sections *d* of the can packages as nested in the traveling can wrapping buckets.

Both forms of the apparatus are equipped with guide devices for outswinging the side wings 34 of the can wrapping buckets 30 when formation of the can packages has been completed. The can packages, however, continue to be supported upon the bottom platform 31 of the opened can wrapping buckets until the buckets arrive at the discharge end of the conveyor. The transportation conveyor, as composed of the hingedly connected buckets, travels around a discharge sprocket 12 which is shaped to cause the bottom platform 31 of the opened buckets to assume a forward inclination sufficient to effect forward sliding discharge of the can package P supported thereon, during initial movement of the bottom platform around the sprocket. A stationary inclined receiver 151 is positioned at the discharge end of the conveyor and is constructed to receive the can package as it slides off the inclined bottom platform of the bucket. The inclined receiver in turn delivers the completed can package onto a suitable belt conveyor 157 for final transportation to any desired location.

The transportation conveyor

The transportation conveyor 10, whose linkages are formed by the hingedly connected can wrapping buckets 30, is supported upon a pair of similar sprockets 11 and 12 rotatably mounted in the framework structure at the head and discharge ends of the apparatus. The framework structure as shown in Figs. 7, 8 and 9 may comprise a pair of longitudinally extending tubular beams 1 which are supported at a convenient elevation by a series of paired tubular supporting posts 2 secured at the lower ends thereof to a corresponding pair of longitudinal beams 3 positioned adjacent the floor. The paired supporting posts 2 may be braced by transversely extending struts 4 to provide a rigid framework structure. The structure may be further braced by a series of upper transverse beams 5 secured to the longitudinal beams 1. Support for the conveyor sprockets 11 and 12 is provided by a pair of longitudinally extending channel shaped beams 6 which extend longitudinally of the conveyor and rest upon the cross beams 5.

Each of the conveyor mounting sprockets 11 and 12 comprises a pair of spaced sprocket forming plates 13 as shown in Figs. 2, 10 and 11 which are maintained in spaced relation by a series of spacing collars 14 and are firmly secured together by tie-bolts 15 which extend through the spacing collars 14. The paired sprocket forming plates 13 are of similar shape and are provided with six radially extending sprocket legs 16 arranged in pairs, with the paired sprocket legs of the paired sprocket plates having aligned semi-circular grooves 16' in the ends thereof designed to engage the hinging axle 43 which connects the link forming buckets 30 of the conveyor. The peripheral edge sections 17 between the adjacent sprocket legs 16 of each sprocket plate 13 has a concave contour so that the sprocket will not interfere with parts of the conveyor forming buckets 30 as they travel around the rotating sprocket.

The paired sprocket forming plates 13 are mounted on a hub section 18 as shown in Figs. 10 and 11 which is splined to a sprocket shaft 19 and adjustably centered on the shaft as by adjustable hub collars 18'. Each sprocket shaft 19 is rotatably journaled in a pair of bearing units 20 each of which is fixed to the adjacent hanger bracket

21. Each hanger bracket 21 has a horizontally extending angle-shaped member 22 secured thereto as by bolts 22' by means of which it is adjustably suspended from the lower flange 6' of the longitudinally extending channel beam 6. Each angle member 22 abuts the bottom flange 6' of the adjacent channel beam 6 and is detachably secured thereto as by a wing locking bar 23. Each pair of hanger brackets 21 may be strengthened and stiffened by an angle shaped bracing strut 24 which may be adjustably connected to the adjacent transverse beam 5 by 10 threaded adjusting bolts 25 as shown in Fig. 10.

By loosening the bolts 23' which secures the winged locking lock bars 23 to the angle members 22 of the hanger brackets 21, and detaching the adjusting bolts 25, the hanger bracket assembly may be detached from the channel shaped supporting beams 6 and the entire conveyor and sprocket assembly removed from the apparatus for adjustment or repair. Additionally, the hanger brackets 21 can also be adjusted in position along the supporting beams 6 to thereby slacken the conveyor 10 to a sufficient extent to permit ready removal of any one of the link-forming buckets 30 thereof, or the addition of link-forming buckets to the conveyor. The conveyor may also be adjusted into stretched operating condition by manipulating the adjusting bolts 25.

The paired channel shaped beams 6 also provide support for the upper run of the conveyor 10 by the provision of a pair of channel shaped guide tracks 26 which rest upon and are secured to the upper flanges 6" of the sprocket supporting beams 6. The paired guide tracks 26 support the conveyor buckets 30 during their upper run travel between the conveyor supporting sprockets 11 and 12. A similar pair of channel shaped guide tracks 27 provide guiding support for the lower run of the conveyor buckets 30 as shown more particularly in Figs. 7, 9 and 11. The lower bucket guiding tracks 27 may be secured to the lower flanges of a pair of longitudinally extending supporting beams 28 which may be secured in suspended position from the transversely extending frame bracing struts 4 previously described. The upper and lower guide tracks 26 and 27, as well as the supporting beams 6 and 28 to which they are attached, are positioned within the loop of the conveyor 10 and extend between the conveyor sprockets 11 and 12 located at the head end and the discharge ends of the apparatus. It will thus be appreciated that the entire transporting conveyor 10, as formed by the hingedly connected can wrapping buckets 30, is continuously supported in predetermined traveling position throughout its entire path of travel by the head sprocket 11, the discharge sprocket 12, the upper guide tracks 26 and the lower guide tracks 27.

The can wrapping buckets

The can wrapping buckets 30, connected to provide the links of the transportation conveyor 10, each comprise a bottom platform 31 as shown in Figs. 16, 17 and 18 having a smooth can supporting surface which is rectangular in shape and sized to the area of the can group to be supported thereon. The bottom platform 31 has a can follower plate 32 extending at a right angle from the rear edge thereof. The can follower plate 32 presents a pair of spaced projecting tongue portions 32' inset from the side edges 33 thereof as shown in Fig. 16.

A pair of side wings 34 are swingably connected to the opposite side edges of the bottom platform 31 as by strong piano hinges 35 and extend substantially the full length of the bottom platform. Each side wing 34 presents a pair of end flanges 36 at the ends thereof whose inner edges 36' may be tapered as shown in Fig. 16 and terminate short of the outer ends 33 of the can follower plate 32' so that the side wing may be erected into vertical position. Each side wing 34 also has an inturned top flange 37 which may be formed integrally with the end flanges 36. The end flanges 36 serve to retain the paired end cans of the can group in alignment when the

side wings 34 are swung into vertical can wrapping position, and the top flanges 37 operate to infold the top panel sections *d* of the wrapper blank as packaged therein. The inside height of each side wing 34 closely approximates the height of the can group as pocketed therebetween, and the side wings 34 are spaced to snugly enwrap the side panels *b* into hugging relation against the sides of the can group. Spaced pressure segments 34' are secured to the inside face of each side wing 34 adjacent the top flange 37 thereof, the pressure segments 34' being so spaced as to exert inbowing pressure on the portions of the blank side panels *b* which extend between the adjacent cans, thereby insuring tight blank wrapping of the can group as shown in Figs. 13 and 15.

Each side wing 34 has a wing supporting roller 38 associated therewith which is rotatably supported on a stub shaft 38' mounted on a bracket 39 secured to and extending laterally from each side wing as shown in Figs. 16, 17 and 18. The side wing supporting rollers 38 are designed to support the side wings in laterally extending position during travel of the can wrapping buckets along the lower run and part of the upper run of the conveyor. Each side wing 34 also has a curvilinear cam plate 40 secured thereto at a point below the side wing 25 supporting roller 38, each cam plate 40 presenting a tapered camming edge 41 which is designed to cam against fixed camming rollers 55 mounted on the framework structure to thereby upswing the side wings 34 as more fully described hereafter.

The bottom platform 31 of each can wrapping bucket 30 has a U-shaped bracket 42 attached to the underside and adjacent the rear end thereof. The U-bracket 42 presents projecting bracket legs 42' through which the bucket supporting axle 43 extends as shown in Figs. 16, 17 and 18. Each end of the axle 43 projects through the adjacent bracket leg 42' and has a ball bearing roller 44 rotatably mounted thereon. The axle 43 is held against weaving movement by a pair of collar portions 43' secured to the axle and positioned adjacent the inside faces of the bracket legs 42'. The following end of each can wrapping bucket is thus supported by its axle 43 and associated rollers 44. The lead end of each bucket is adjustably clamped to the supporting axle 43 of the next preceding can wrapping bucket so that both ends of the buckets are supported by the intervening axles 43 and associated rollers 44 in a manner to provide a continuous conveyor.

A stiffening plate 45 is secured to the underside of each bottom platform 31 and extends from the axle supporting U-bracket 42 to the leading edge of the platform. The stiffening plate 45 is provided with a downwardly extending coupling flange 46 as shown in Figs. 17 and 18. A detachable coupling plate 47 is secured to the coupling flange 46 as by connected bolts 47'. The adjacent faces of the coupling flange 46 and coupling plate 47 define an axial hole 47' therebetween which is designed to embrace the center section of the preceding bucket axle 43 to thus provide the hinging linkage between adjacent buckets. The bottom platform 31 may be further strengthened and reinforced by stiffening angles 48 positioned on each side of the stiffening plate 45. Each of the stiffening angles 48 presents a horizontal leg portion 49 secured to the underside of the bottom platform 31, a vertically extending leg portion 49' which abuts against the side edge of the stiffening plate 45, and an end flange portion 49" which seats against the adjacent edge of the U-bracket 42. As thus reinforced, the can wrapping buckets are strong and sturdy in construction and provide the linkages for the transportation conveyor 10 whose linkage lengths are measured by the distance between adjacent bucket-supporting axles 43.

It will be noted by referring to Figs. 10 and 11 that the adjacent axles 43 associated with the can wrapper buckets are equally spaced and conform to the spacing between the sprocket legs 16 of the conveyor sprockets

11 and 12, and that the paired sprocket plates 13 are so spaced that the axle supporting grooves 16' thereof will engage the spaced sections of each axle which extends between the adjacent collar portion 43' and the adjacent downwardly extending leg portion 49' of the bucket stiffening angle 48.

It will also be noted by referring to Figs. 8, 9, 10, 11 and 12 that the upper run of the can wrapping buckets are supported by the upper channel shaped guide tracks 26 into which the bucket supporting rollers 44 extend. The bucket supporting rollers 44 actually roll on the bottom flanges of the guide tracks and are prevented from moving out of rolling contact therewith by the overhanging flanges thereof. The ends of the guide tracks 26 as shown in Figs. 8 and 10 terminate directly above the head and discharge sprockets 11 and 12 so that when the axles 43 of the traveling buckets move away from the advance ends of the guide tracks 26, they are picked up and supported in the axle grooves 16' in the adjacent legs 16 of the discharge sprocket 12. Also, when each bucket supporting axle 43 is discharged from supporting position on the sprocket legs 16 of the head sprocket 11, it is so directed that the bucket rollers 44 are projected into the entry end of the guide tracks 26. In the same manner, the lower pair of roller guiding tracks 27 cooperate with the head and discharge sprockets 11 and 12 so that the adjacent paired sprocket legs 16 of the discharge sprocket 12 will discharge the bucket axle 43 supported thereon into the entry end of the lower guide tracks 27, and the legs 16 of the head sprocket 11 will pick up the axle when leaving the discharge end of the lower guide tracks 27.

The apparatus is also equipped with a pair of upper wing supporting guide tracks 50 and a pair of lower wing supporting guide tracks 53 which cooperate with the side wing rollers 38 to support the wings of each bucket in horizontally extending position as shown in Figs. 8, 11 and 12 for a substantial part of their travel. The Z-shaped tracks 50 may be supported in proper operating position on the transverse beams 5 of the framework structure and present substantially flat and horizontally extending roller supporting faces 51 and curvilinear end sections 51' having an angular radius of 90° or more at the head end of the apparatus. The curvilinear sections 51' are so shaped and formed as to maintain the side wings 34 of the buckets substantially in horizontally extending position, and in a position to receive the substantially flat wrapper blank as deposited into the opened bucket by the blank feed mechanism 70 during their advance around the upper half portion of the head sprocket 11. The curvilinear sections 51' may be rigidly supported by suitable brackets 52 attached to the adjacent framework structure. The discharge end 50' of the upper wing supporting tracks 50 terminate at a point approximately midway of the length of the can packaging apparatus and are thence replaced by a pair of wing supporting rails 57 constructed as hereafter described.

Since the side wings 34 of the buckets perform no operating function during their travel along the lower run of the bucket forming conveyor, the wings 34 are supported in inverted and horizontally extending position as shown in Fig. 11 during the entire lower run travel of the buckets by a pair of wing supporting tracks 53 which are generally Z-shaped in cross section, as shown in Figs. 7, 8, 9, 11 and 12, and which are supported by the transverse struts 4 of the framework structure. The wing supporting tracks 53 present a flat track-forming flange 54 on which the wing rollers 38 may roll. The head ends of the wing supporting tracks 53 are provided with curvilinear track forming extensions 54' which extend upwardly and partly overlap the curvilinear end sections 51' of the upper wing supporting tracks 50. Thus when the side wing supporting rollers 38 move off from the inner face of the curvilinear track sections 54', they will move into rolling contact with the outer face of the curvilinear

track sections 51' of the upper wing supporting tracks 50. A similar pair of curvilinear track sections 54" extend upwardly from the lower tracks 53 at the discharge end of the apparatus and are positioned to provide support for the wing rollers 38 as they move downwardly around the discharge sprocket 12. The curvilinear track sections 54' and 54" may be supported by suitable brackets 52' attached to the adjacent framework structure.

The side wing manipulating system of this apparatus 10 also includes means for upswinging the side wings 34 of the traveling buckets as they move away from the can loading station, and means for maintaining the side wings 34 and the side panels *b* of the wrapper blanks pocketed therein in hugging position against the sides of the can 15 group until the top panel sections *d* of the wrapper blank have been fixedly secured together over the upper end of the can group. Upswinging movement of each side wing 34 of the traveling buckets is effected by a series of cam 20 rollers 55, each roller series being rotatably supported on an upward projecting support plate 56 on which the rollers 55 are mounted at a progressively higher elevation as shown in Figs. 7, 14 and 15. The two cam roller supporting plates 56 may be secured to the side faces of the upper pair of bucket supporting beams 6. Each series 25 of cam rollers 55 are so mounted as to be engaged by the tapered camming edge 41 of the cam plate 40 of the traveling side wing 34 as above described, and thereby upswing the side wings 34 of each can wrapping bucket during the continuous travel thereof adjacent the can 30 roller supporting plates 56.

The paired cam rails 57 serve to maintain the side wings 34 in upright position and in closely hugging relation to the can package therebetween during the travel of the buckets along the stapling or gluing station. The 35 paired can rails 57 may be angle shaped in cross section, as shown in Figs. 7, 8 and 15 and so formed that each rail 57 presents a vertical flange section 58 which extends parallel to the line of travel of the buckets and against which the adjacent wing roller 38 may roll. The 40 entry ends 58' of the rail forming flange sections 58 flared outwardly as shown in Fig. 8 to provide smooth entry of the wing rollers 38 as the tapered camming edges 41 of the wing camming plates 40 move away from the influence of the upswinging cam rollers 55.

The vertical rail sections 58 extend for a sufficient 45 length to assure firm securing of the infolded top panel sections *d* of the wrapper blank during travel of the can package through the stapling or gluing station. The vertical rail sections 58 then merge into the outwardly flaring sections 59 which become gradually flattened to 50 permit outswinging movement of the bucket side wings 34 near the discharge end of the apparatus as shown in Fig. 8. The outwardly flared sections 59 further merge into 55 downwardly extending curvilinear sections 60 designed to support the side wings 34 in horizontal position during their travel around the upper half section of the discharge sprocket 12. The curvilinear sections 60 are partly overlapped by the upwardly extending curvilinear sections 54" associated with the lower side wing supporting 60 tracks 53 previously described. Thus during the bucket travel around the discharge sprocket 12, the outfolded side wings 34 are first supported by the downwardly extending curvilinear track sections 60, and thence their weight is transferred to the upwardly extending curvilinear sections 54' associated with the lower guide wing supporting tracks 53.

To positively insure the outswinging movement of the 70 vertically extending side wings 34 during their travel from the vertical rail sections 58 onto the outwardly curving rail sections 59, a pair of guide plates 61 are provided which extend between the paired wing rollers 38 as shown in Figs. 9 and 13. The paired guide plates 61 have inwardly flared entry ends 61' and outwardly flared exit ends 61" to insure smooth entry and exit of the wing 75 rollers 38 between the guide plates 61 and the adjacent

track sections 58 and 59 of the cam rails 57. Positive outswinging movement of the side wings 34 upon completion of the can package is thus assured.

The paired cam rails 57 and associated guide plates 61 may be supported from the framing structure of the apparatus by any desired supporting means. Said supporting means, as shown in Figs. 8, 13 and 15, may comprise a pair of spaced and transversely extending frame bars 62 and 62' each of which is supported by a pair of pedestal brackets 63 which may be secured to the adjacent longitudinally extending main beams 1 of the framework structure. A pair of longitudinally extending frame members 64 may be secured to each pair of pedestal brackets 63. The horizontally extending flange of each cam rail 57 may be adjustedly secured as by bolts 65 to the adjacent longitudinally extending frame member 64. The outwardly flaring sections 59 and the downwardly extending curvilinear sections 60 of the cam rails 57 may be supported by suitable brackets 66 attached to the main side beams 1 as shown in Fig. 8. The guide plates 61 may also be supported in suspended position from the adjacent transversely extending frame bar 62'.

Blank feeding and depositing mechanism

The blank feeding and depositing mechanism 70 as shown in Figs. 1, 2, 7, 8, 10 and 11 is designed to remove the successive end-most wrapper blanks from a stack of blanks supported in a supporting tray 71 and deposit each blank in each of the expanded can wrapping buckets. The supporting tray 71 presents an inclined bottom panel plate 72 on which the lower horizontal edges of the stacked blanks may rest, the blanks being maintained in aligned position by side walls 73 associated with the tray. The tray may be reinforced by a pair of transverse frame members 74 and 74' supported at different elevations to maintain the bottom plate of the tray in inclined position. Support for the transverse frame member 74 and 74' of the tray may be provided by side frames 75 attached to supporting legs 76 which may in turn be secured to the main beams 1 of the frame structure. The front frame member 74 as shown in Fig. 10 may be suitably secured to the side frames 75 and the rear frame member 74' may be supported in elevated position by suitable pedestal supports 77 which may rest on the side frames 75.

The successive end-most blanks may be ejected from the blank supporting tray 71 by a feed cylinder which may comprise a plurality of spaced blank feeding discs 78 of substantially equal diameter which are fixed to a horizontally extending supporting shaft 79. Each blank ejecting disc 78 may be provided with a raised blank ejecting pad 80 which may be made of rubber or the like and designed to withdraw the end-most blank over the discharge end 72' of the inclined bottom wall plate 72 of the tray. The ends of the shaft 79 may be supported in suitable bearing blocks 81 which rest on the side frames 75. A drive sprocket 82 may be attached to the projecting end of the feed disc supporting shaft 79 and over which a drive chain 83 may be trained. The drive chain 83 is preferably operably connected to the driving mechanism which drives the bucket conveyor 10 so that the successive blanks are deposited into the successive expanded buckets 30 in synchronism with the travel movement of the conveyor.

It will be noted by referring to Fig. 10 that the end-most blank as withdrawn from the blank tray 71 is projected downwardly onto the bottom platform 31 of the adjacent bucket during its inclined rise over the upper half of the feed sprocket 11. As thus fed, the lower edge of the ejected blank is driven against the can follower plate 32 associated with the rising bottom platform 31 to thus insure placement of the blank in proper position within the expanded can wrapping bucket.

The blank supporting tray may also be provided with a suitable follower weight 84 designed to slide on the bottom forming plate 72 of the tray as shown in Fig. 10. To insure proper transverse alignment of the wrapper

blank as deposited within the expanded can wrapping bucket, the apparatus is also provided with a pair of chute forming side plates 85 as shown in Figs. 10 and 11 which are spaced apart a distance which closely approximates the overall length of the flat wrapper blank. Each blank guiding plate 85 may be adjustably secured as by suitable stud screws 86 to the adjacent supporting posts 76 of the framework structure and have their terminal ends 85' positioned adjacent the can loading station.

Can driving, grouping and loading mechanism

The can driving, grouping and loading mechanism 90 as illustrated in Figs. 1, 2, 7, 8, 9 and 12 comprises a pair of can driving rotors 91 positioned at opposite sides of the package forming line of the apparatus. Each of the can driving rotors 91 comprises a circular can platform 92 which extends in a horizontal plane slightly above the level of the horizontally traveling bottom platform 31 of the expanded can wrapping buckets during their travel between the can driving rotors 91. Each circular can platform 92 is supported by a hub 93 and secured thereto by suitable attaching bolts 93'. Each hub 93 presents a vertically extending socket 94 which telescopes over the upper end of a stub shaft 95 and is clamped thereto so that the can platform 92 is rotated by the stub shaft 95. A rotor elevating set screw 96, as shown in Fig. 12, extends axially through the vertically extending hub 93, with its end portion designed to seat against the upper end of the stub shaft 95. By a proper adjustment of the set screw 96, the can driving rotor 91 may be nicely adjusted to place its can supporting platform 92 at the proper operating elevation.

The lower end of each stub shaft 95 extends into a gear box 97 and has a beveled gear 98 attached thereto which meshes with a companion beveled gear 98' fixed to the end of a drive shaft section 99. The two drive shaft sections 99 associated with the two can driving rotors 91 extend to the approximate longitudinal center line of the apparatus, and are secured together by a shaft coupling 100 as shown in Fig. 12. Each of the gear boxes 97 and associated can driving rotors 91 are supported upon a supporting shelf 101 which may be suitably secured to the adjacent supporting posts 2 of the frame work structure. The coupled shaft sections 99 are driven in unison by a sprocket 102 attached to one of the sections over which a drive chain 102' is trained and driven in synchronism with the advance movement of the bucket conveyor.

The circular can platform 92 of each can driving rotor 91 is provided with a tubular core 103 which is suitably secured to and centered around the axial center of the can platform 92 as shown in Fig. 12. The tubular core 103 has a pair of spaced and horizontally extending can driving star discs 104 attached thereto whose peripheries present a series of arcuate can receiving cells 105 dimensioned to substantially conform to the circumference of the cans to be packaged and designed to embrace approximately a third to one-half of the circumference of each can as shown in Figs. 1, 8 and 12. It will be noted that the periphery of each can platform 92 extends beyond the periphery of the arcuate can receiving cells 105 of the can driving discs 104 so that a peripheral section of the can platform 92 will fully support the cans as placed thereon and set within the cells 105 of the can driving discs 104.

A row of cans is supplied to each can driving rotor 91 by a suitable can conveyor line 106 along which the cans may either be pushed, or carried by a driven bottom belt, associated with the can conveyor line. The can conveyor lines 106 may be directed to supply cans from a direction adjacent the discharge end of the conveyor, or alternatively, can feeding lines 106' may be provided to supply the cans from a direction adjacent the head end of the apparatus as shown in Fig. 1 or from any other desired direction.

Each of the can driving rotors 91 has a U-shaped table

plate 107 positioned in surrounding relation to, and in the plane of the can platform 92 thereof as shown in Figs. 1, 7, 8, 9 and 12. One leg of the table plate 107 provides an entry section 108 onto which the cans are directed and pushed or driven by the can conveyor line 106 or the alternative conveyor line 106'. The cans are maintained upright as they are driven upon the entry section 108 of the table plate which may have a depressed can entry edge directly adjacent the conveyor line to assure smooth movement of the erected cans onto the entry section 108. The table plate 107 is also provided with a can exit section 109 onto which the cans are driven by the associated can driving rotor 91. The discharge edge of the can exit section 109 extends in close proximity to but slightly above the elevation of the adjacent side edge of the bottom platform 31 of the expanded buckets during their travel adjacent thereto.

Each of the table plates 107 are fixedly supported by suitable framing which may comprise a longitudinal frame member 110 on which the outer side edge of the table plate 107 may be supported. The table framing may also comprise a pair of spaced and transversely extending table frame members 111 and 112 as shown in Figs. 7, 8, 9 and 12. A pair of spaced vertical supports 113 may be secured to the adjacent longitudinally extending main beam 1 of the framework structure and suitably secured to the underside of the table plate 107 to support the table plate at the proper elevation. To strengthen the construction, the aligned ends of the transverse frame members 111 of the two table plates 107 may be connected as by a suitable tie strut 111', and the aligned ends of the other pair of transverse frame members 112 may be secured to an upwardly arched frame section 112' as shown more particularly in Fig. 9 to thereby stiffen and strengthen the supporting framework of both table plates 107.

The can supply moving onto the entry section 108 of each table plate 107 is guided in its movement by a feed trough which comprises an inner guide wall plate 114 and an outer guide wall plate 115 as shown in Fig. 1. The inner guide wall plate 114 has its terminal end directly adjacent the path of travel of the can driving star discs 104. The companion guide wall plate 115 has an arcuate section 116 designed to retain the cans in driving engagement with the can receiving cells 105 of the paired star discs 104 as shown in Fig. 1. The cans in the can feed line are driven onto the can platform 92 of each can driving rotor 91 and are thereby transported and maintained in the cells thereof by the arcuate section 116 of the outer can guide wall.

The cans are then guided off from the can platform 92 of each can driving rotor 91 and pushed, while in upright position, diagonally across the exit section 109 and off from the discharge edge thereof. The can discharge trough comprises an outer guide plate section 117 which forms a continuation of the arcuate section 116. The two outer guide plate sections 117 extend forwardly and are joined together to form a relatively acute V-angle and secured to a narrow vertically extending bracket strut 117' as shown in Fig. 13 which is fixed to the adjacent framework. The companion guide plate 118 of the exit trough has an entry end 118' which is curvilinear in form and positioned closely adjacent the path of rotation of the outer periphery of the paired can driving discs 104 as shown in Fig. 1. The exit end of the companion guide plate 118 terminates in an outwardly flared exit portion 118" which extends slightly beyond the discharge edge of the exit section 109 of the table plate 107. The can driving rotors 91 thus drive the cans diagonally across the exit sections 109 of the table plates 107, as guided by the trough forming plates 117 and 118, until the lead cans in the two can rows are pushed across the bottom portion α of the blank A which is carried on the traveling bottom platforms 31 associated with the expanded can wrapping

buckets 30 as shown more particularly in Figs. 12, 13 and 19 to 23 inclusive.

It will be noted that the trough forming sections 117 and 118 are positioned above the can follower plate 32 extending upwardly from the rear edge of the bucket platform 31 and thus do not interfere with the travel of the can follower plates 32 advancing between the wall sections 117 of the converging can troughs. It will be further noted by referring to Figs. 19 to 23 inclusive that the side wall sections 117 and 118 of the converging troughs guide the cans forwardly at an acute angle and the cans are held in erect position as the bottom ends of the cans are moved completely off from the adjacent inner discharge edges of the two exit sections 109 of the table plates 107. The discharge edges of the can supporting exit sections 109 also extend parallel to and only slightly above and directly adjacent to the side edges of the traveling bucket platforms 31, thereby insuring smooth grouping disposition of both lines of cans onto the bottom panel of the blank as disposed on the traveling bucket platforms 31. The trough forming guide plates 114, 115, 116, 117 and 118 may be supported by angular brackets 119 fixed to the table plates 107.

As shown in Figs. 10 and 12, the side wings 34 of the expanded buckets extend in a horizontal position with the end portions of the flat wrapper blank resting on the free horizontal edge of the top flanges 37 of the fully expanded bucket side wings 34, and with the bottom panel α of the blank supported on the bottom platform 31 as they advance directly under and closely adjacent to the underside of the exit sections 109 of the table plates 107. To insure unobstructed entry of the flat blanks directly under the entry edge of the table plates 107, two or more guide shoes 120 may be provided as shown in Fig. 10 to thereby 35 guide the end portions of the blank resting on the horizontally extending bucket wings 34 directly beneath the leading edge of the table plate 107. Each of the shoes 120 may be formed of resilient metal and may have an upturned heel portion 120' which may be secured as 40 by screws 120" to the adjacent transversely extending frame member 111 of the table plate. Smooth movement of the flat wrapper blanks under and directly adjacent to the undersurface of the table plates 107 is thus assured.

When the can group has been accurately loaded onto the bottom panel α of the flat blank, in progress as shown in Fig. 23 and completed as shown in Fig. 13, the side wings 34 of the traveling bucket swing upwardly as shown in Fig. 14 as a result of the engagement of the cam edge 41 of the wing cam plate 40 with the upwardly 45 rising series of cam rollers 55 as previously described. When the side wings 34 have been fully erected as shown in Fig. 15, the side panels b of the wrapper blank will be pressed into hugging engagement with the sides of the can group and the inturned top flanges 37 of the 50 side wings 34 will automatically fold the top panel sections d of the wrapper blank inwardly. When the side wings 34 have been fully erected as shown in Figs. 13, 15, 26 and 28, the end flanges 36 of the bucket side wings 34 will overlap a portion of the end cans and thereby maintain the can group in compact alignment. The side wings 34 are maintained in erect position during 55 the travel of the side wing rollers 38 along the adjacent vertical rail flanges 58 of the can rails 57, and the side wings are so maintained until the top panel sections d of the enwrapped blank have been firmly secured together as by staples or adhesive.

Handle upfolding and securing mechanism

Where a can wrapper blank is provided with paired handle sections f which must be upturned and secured together, the apparatus is equipped with an overhead handle upfolding blade 121 as shown in Figs. 2, 8, 13, 14 and 15 which extends longitudinally along the center line of the bucket forming conveyor. The handle upfolding blade 121 may be supported in suspended posi-

tion by a longitudinally extending bar 122 one end of which is secured as by a vertical leg 123 secured to the arch section 112' which connects the transverse table frame members 112 as previously described. The other end of the suspension bar 122 may be suitably secured to the transverse framing bar 62 as shown in Fig. 7. The handle upturning blade 121 may also be provided with a can separating belly section 121' as shown in Fig. 14 which assists in aligning the cans onto the bottom panel *a* of the wrapper blank before the bucket side wings 34 are upturned. The belly section 121' merges into the handle upturning section of the blade just before the side wings are fully upturned. When the side wings have been almost fully upturned, the top panel sections *d* of the blank will start to fold over the top end of the can group, and the handle sections *f* extending therefrom will be swung into abutment against the side faces of the handle upturning blade 121 to thereby upfold the handle sections *f* thereagainst when the side wings 34 have been fully erected.

To provide support for the underface of the inturned top panel sections *d* of the blank, a thin longitudinally extending backing plate 124 as shown in Fig. 15 may be secured to the lower edge of the handle upturning blade 121. The thin backing plate 124 may extend forwardly of the terminal end of the handle upturning blade 121 to also provide support for the inturned top panel sections of the blank during the handle stapling operation.

To maintain the inturned top panel sections *d* of the can wrapper blank in horizontally extended position over the upper end of the can group, a pair of resilient shoe plates 125 may be provided as shown in Figs. 7, 13 and 15 which extend between the inner edges of the inturned top flanges 37 of the erected side wings and are separated sufficiently to permit the overlapped pair of handle sections *f* to extend upwardly therebetween. The entry end of the paired shoe plates 125 are provided with rounded and upwardly extended heel portions 126 which may be secured to the adjacent overhead transverse frame bar 62. The discharge end of the shoe plates 125 present upturned toe portions 127 which are positioned in close proximity to the stapling mechanism 128 as shown in Fig. 13.

The stapling mechanism 128 is designed to apply two or more spaced staples *s* to the paired and erected handle sections *f* during travel of the can packages between the transverse frame bars 62 and 62' when the side wings 34 of the package containing buckets are in fully erected position. The stapling mechanism 128 may include a stapling arm 129 having associated staple forming and driving devices designed to apply the staples *s* to the paired handle sections *f* during continuous travel of the can packages and while the inturned top panel sections *d* of the wrapper blank are supported upon the thin backing plate 124 which extends under the stapling arm 129 and between the top face of the can group and the underface of the inturned top panel sections *d*. The particular construction of the stapling mechanism 128 does not constitute a part of this invention and therefore will not be further described. When the paired handle sections *f* have been secured together as by staples *s*, and have advanced away from the stapling mechanism 128, the wing cam rollers 38 of the buckets are engaged by the inner guide plates 61 to swing the side wings 34 outwardly so as to permit final discharge of the completed can package from the bucket conveyor.

Top panel gluing and securing mechanism

Where a blank A' in the form shown in Fig. 5 is to be used to form the can package, the stapling mechanism 128 may be eliminated and glue applying devices 130 and pressure devices 140 for applying pressure to the glued and inturned top panel section *d* of the blank may be substituted. As shown in Figs. 24 to 27 inclusive,

the glue applying device 130 is arranged to apply two parallel strips *i* of adhesive on each side of the finger holes *j* of one of the top panel sections *d* of the blank formed as shown in Fig. 5. The glue applying device 5 130 may be positioned closely adjacent one of the table plates 107 and may be supported from the adjacent frame members 112 and 113 of the apparatus.

The glue applying device 130 may comprise a pair of relatively large rolls 131 for supporting that portion of 10 one of the top panel sections *d* which overhangs the top flange 37 of the expanded side wing 34 during its travel beyond the adjacent table plate 107. The blank supporting rollers 131 may be freely rotatable, but preferably are driven rolls fixed to a stub shaft 132 journaled in 15 supporting brackets 133 suitably supported by the adjacent side beam 113. Glue is applied to the upper face of the overhanging blank extension by a pair of spacer glue applicator rollers 134 fixed to a stub shaft 135. The peripheral surfaces of the glue applicator rolls 134 receive 20 a film of adhesive from a corresponding pair of glue transfer rollers 136 which may be rotatably journaled on a stub shaft 137.

The glue or adhesive may be contained within a glue pot 138 having a pair of discharge spouts 138' for supplying 25 adhesive to the peripheral surfaces of the glue transfer rolls 136. The stub shafts 135 and 137 may be rotatably mounted in a bearing block 133' which is secured on the frame member 112. The glue pot 138 is mounted in its operative position above the glue transfer rolls 136 by means of an angle bar 138" which in turn is secured to the raised section 112' of frame member 112 and extends outwardly to the appropriate position. The shaft 132 which carries the blank supporting rollers 131, and the stub shaft 135 to which the glue applicator rolls 30 134 are secured, are rotatably journaled in suitable bearings carried by the supporting brackets 133'. The end extensions of the stub shafts 132 and 135 may be provided with suitable meshing gears 139 and shaft 132 is further provided with a drive sprocket 139' over which 35 a drive chain 139" is trained. The blank supporting rollers 131 and glue applicator rollers 134 are thus driven at the same speed and in opposite directions to pass the blank between them without disturbing the blank speed as determined by the advancing speed of the blank carrying bucket 30. Thus the glue applying device 130 operates 40 to apply the paired longitudinally extending strips of adhesive *i* to the overhanging portion of one of the top panel sections *d* while the wrapper blank is in full expanded condition and immediately before the bucket side wings 34 are swung into upright position by engagement of the cam edge 41 of the wing cam plate 40 with the fixed cam rollers 55.

It will be noted by referring more particularly to Fig. 25, that the cam rollers 55 of the cam roller support plate 55 56 on the upper half of Fig. 25, is positioned in advance of the companion cam roller supporting plate so as to thereby upfold the bucket wing 34 on the upper side of the conveyor line, and which supports the top panel section *d* of the blank which has no glue applied thereto, in 60 advance of the upswinging movement of the companion side wing 34 on the lower side of Fig. 25, which supports the blank top panel section *d* to which the glue strips *i* have been applied. Thus the unglued top panel section *d* is fully infolded in overlying relation to the top end of the can group before the glued top panel section *d* is infolded, and so that the glue strips *i* applied thereto will be placed in adhering relation to the underlying and previously inturned top panel section *d*. In this form of the invention the overhead handle upfolding blade 121 is eliminated so that no obstruction is presented to the overlapped infolding of the top panel sections *d*.

The device 140 for applying pressure to the infolded and overlapped top panel sections *d* of the blank form of Fig. 5, may be supported from the transverse frame bars 75 62 and 62' as shown in Figs. 25 and 26. The pressure

device 140 may comprise a continuous pressure belt 141 having a width designed to extend between the inner edges of the infolding top flanges 37 of the bucket side wings 34 as fully erected. The pressure belt 141 may be supported by a pair of end rollers 142 and 143. The end roller 143 is fixed to a driven shaft 144 rotatably journaled in supporting brackets 145 which may be connected to the transverse frame member 62'. The drive shaft 145 may be provided with a drive sprocket 146 around which a drive chain 146' is trained. The other belt supporting roller 142 may be mounted for free rotation on a shaft 147 supported by suitable brackets 147' connected to the transverse frame member 62. A pressure shoe 148 is preferably provided to maintain the lower run of the pressure belt 141 in proper pressure contact against the infolded top panel sections *d* of the wrapper blank and may be supported by resilient struts 149 and bars 149' mounted on the framework members 62 and 62' to maintain the lower run of the belt 141 in resiliently pressed engagement with the infolded top panel sections *d* of the can package.

Employment of the pressure belt 141 as supported between the transverse frame bars 62 and 62' permits elimination of the shoe plate 125 shown in Fig. 13 as well as the stapling mechanism 128. When the inturned top panel sections *d* of the can package have become firmly adhered together as a result of the pressure applied to the overlapped top panel sections by the pressure belt 141, the bucket wings 34 are swung away from the can package as a result of the engagement of the wing rollers 38 with the guide plates 61.

Can package discharge mechanism

When the stapling or gluing operation has been completed, the completed can packages P are in condition for discharge from the bucket conveyor. In both forms of the invention, the bucket side wings 34 are swung into opened horizontal position and are so supported by the end sections 59 and curvilinear sections 60 of the side wing supporting rails 57. The can packages nevertheless remain supported upon the advancing bottom platforms 31 of the expanded can wrapping buckets as they approach the discharge end of the apparatus.

It will be noted that each bucket platform 31 presents an unobstructed advance edge and that the can follower plate 32 extends along only the rear edge thereof. Thus when the can package supporting platform 31 moves around the six-sided discharge sprocket 12 as shown in Figs. 1, 2, 7 and 8, the bucket platforms 31 will assume an increasingly tilted position as they move over the upper half of the discharge sprocket 12. When the can package supporting platform 31 has been tilted forwardly at an angle of approximately 30° to the horizontal, the preceding platform 31 will have been tilted to substantially a vertical position, in which position the can follower plate 32 of the advance platform 31 will extend in substantially a horizontal position. Thus when the following can package supporting platform has been progressively tilted at an angle of approximately 30° or more, the follower plate 32 of the preceding platform offers no obstruction to the forward sliding removal of the can package.

The can package discharge mechanism 150 as shown in Figs. 2, 7, 9 and 24 includes a can package receiving trough 151 which is supported in inclined position and presents a smooth inclined bottom wall 152 and spaced side walls 153 which serve to guide the package as it slides over the bottom wall 152. The side walls 153 have flared entry ends and the receiving edge of the inclined bottom wall 152 may also be provided with a downward bent entry portion to facilitate reception of the discharging can package thereon.

The discharge tray 151 may be adjustably supported on a transverse frame member 154 which may be secured to the end extensions 155 of the side beams 1. The dis-

charge tray 151 is adjustably mounted on the transverse frame member 154 by an adjustable bracket 156 so that the inclination of the bottom wall 152 of the tray, as well as the position of its receiving end with respect to the packages undergoing discharge from the bucket platforms 31, may be adjusted as may be required. As the can packages slide off the discharge chute 151 they may be delivered directly onto the upper run of a suitable belt conveyor 157 for transportation to any desired location.

Driving mechanism

All the moving parts of the can packaging machine of this invention are driven in synchronism and may be driven from a single driving motor 160 as shown in Fig. 28 having a gear reducing unit 161 associated therewith which drives the main power sprocket 162. A suitable speed adjusting device 163 may be associated with the speed reducer 161. The driving motor 160 and associated speed reducer 161 may be supported on a platform 164 as shown in Fig. 7 which extends under the main frame structure and may be slidably supported on the lower tubular beams 3.

The power sprocket 162 transfers its driving power to the main drive chain 165 which drives a sprocket 166 fixed to the main drive shaft section 167. The main drive shaft section 167 may be connected to a companion drive shaft section 167' through the agency of a bevel gear 169 fixed to the shaft section 167, which may drive an intermediate beveled gear 169', and which in turn drives a companion beveled gear 169" fixed to the companion shaft section 167'. The intermediate beveled gear 169' may be employed to drive the shaft 168 of the stapling mechanism 128, where a stapled type of blank is employed.

The platform conveyor 10 is operated by rotating the conveyor supporting sprocket 12 at the discharge end of the apparatus, and may be driven from the companion shaft section 167' which has a drive worm 170 attached to the end thereof. The drive worm 170 meshes with a worm wheel 171 fixed to a transverse shaft 172 having a driven sprocket 173 affixed thereto. The driven sprocket 173 carries a drive chain 174 which is trained around a sprocket 175 fixed to a shaft section 19' extending from the supporting shaft 19 of the discharge sprocket 12.

The can driving rotors 91, supported by the stub shafts 95 and driven from the coupled shaft sections 99 by the sprocket 102 attached thereto, may be driven from the main drive shaft section 167 of the driving mechanism. The main drive shaft section 167 has a driving worm 176 attached thereto which meshes with a worm wheel 177 fixed to a transverse shaft 178 which carries a driven sprocket 179. The driven sprocket 179 drives the sprocket chain 102' which is trained around the rotor driving sprocket 102 previously described. An idler sprocket 179' may also be provided to maintain the drive chain 102' relatively taut.

The blank feeding discs 78 fixed to drive shaft 79 and to which the sprocket 82 is attached, is driven by drive chain 83 from a longitudinally extending auxiliary shaft 180 which is mounted to rotate in suitable bearing blocks 180' attached to the supporting posts 2 and 76 on one side of the machine as shown in Figs. 11 and 12. The auxiliary shaft 180 carries a sprocket 181 around which a drive chain 182 is trained. The drive chain 182 is driven by a sprocket 183 fixed to the companion shaft section 167' as shown in Fig. 28. The longitudinally extending auxiliary shaft 180 has a beveled gear 184 attached thereto which meshes with beveled gear 185 fixed to a transverse shaft 186 to which a driving sprocket 187 is fixed. The drive chain 83 which drives the blank feeding discs 78 as heretofore described is trained around the driving sprocket 187. The auxiliary shaft 180 and some of the operating mechanisms directly or indirectly connected thereto, may be conveniently rotated by hand

cranks 180" connected to the ends thereof when making adjustments to the mechanisms.

Where a blank such as shown in Fig. 5 whose top handle sections *d* are to be glued together is employed, the stapling mechanism operating shaft 168 as shown in Fig. 28 may be eliminated, and in substitution therefor, driving means is provided to drive the chain 139" which rotates the blank supporting rollers 131 and the glue rollers 134. Thus, the drive chain 139" may be driven from a sprocket 190 fixed to an extension 99' of the shaft 99 as shown in Fig. 28. The pressure belt 141 which is driven by the drive chain 146' may be trained around a sprocket 191 fixed to a stub shaft 192 on which is also fixed a gear 193. Meshing with the gear 193 is a similar gear 194 which is fixed to the end of an extension 172' of shaft 172. It will be appreciated that all the driving gears and sprockets are so sized and proportioned as to drive the operating mechanisms in proper synchronism and direction and so that the entire packaging operation may be performed automatically and with a minimum of attention.

Method of operation

In operating the can packaging apparatus of this invention, the blank supporting tray 71 is supplied with blanks and the driving motor 160 which drives all operating mechanism in synchronism is placed in operation. The blank feeding discs 78 operate to eject successive end-most blanks as shown in Fig. 10 in synchronism with the advance movement of the bucket conveyor 10 so that a blank is placed on the bottom platform 31 of each successive can wrapping bucket as the bottom platform rises over the upper half section of the head sprocket 11.

Each blank as thus deposited has the lower horizontal edge thereof positioned in abutment against the can follower plate 32 of the bucket platform on which it is supported. The blank guiding plates 85, adjustably mounted and spaced to closely approximate the transverse width of the blank, assures accurate centering of the blank bottom panel *a* on the bottom platform 31 of the expanded bucket. It will also be noted by referring to Fig. 10, that the longitudinal length of the blank bottom panel *a* closely approximates the longitudinal length of the bucket platform 31, so that the advancing front edge of the blank is closely adjacent to the can follower plate 32 of the preceding bucket when the rear edge of the blank is in abutment against the follower plate 32 of the platform on which it is supported. As a result, each blank is properly centered on the expanded bucket during its advance to the can loading station.

The expanded bucket with the flat wrapper blank supported thereon, continues its advance directly under the table plates 107, and the can group is deposited on the bottom panel *a* of the blank as it advances between the parallel extending discharge edges of the can exit sections 109 of the table plates. The can driving rotors 91 are driven in synchronism with the advance movement of the bucket conveyor 10 to advance the two can lines diagonally and forwardly across the exit sections 109 of the table plates 107 as shown in Figs. 1, 12 and 13 and Figs. 19 to 23 inclusive, and in a manner so that the speed of forward advance of the exit can lines is equal to the advance speed of the top run of the bucket conveyor.

Where the blank bottom panel *a* and the bucket platform 31 on which it rests, is proportioned to receive a group of six cans as shown in Fig. 23, the first pair of cans are pushed off the discharge edge of the table exit sections 109 on the front third area of the blank bottom panel, the next pair of cans are pushed onto the middle third area of the blank bottom panel, and the third pair of cans are pushed onto the rear third area of the blank bottom panel. It will be noted by referring to Fig. 23 that the side edges 33 of the can follower plate 32 knife

between the last pair of cans undergoing loading on the blank bottom panel and the first pair of cans to be loaded on the following blank bottom panel. Thus the can follower plates 32 serve to effect the desired grouping of the cans in the process of loading. Since the can discharge chutes, as defined by the forwardly extending guide plate sections 117 and 118, are located above the top edge of the advancing can follower plates 32, there is no interference to the advance movement of the follower plates 32 or their associated bucket platforms 31.

It will be further noted that the side plate sections 117 and 118 of the exit chutes maintain the cans in erect position and direct the adjacent sides of the paired cans into abutment when placed on the bottom panel *a* of the blank. Since the successive cans in the discharge chutes are being pushed onto the blank bottom panel, they are also maintained in snug abutment. Close nesting of the cans comprising the group desired for packaging is thus assured.

When the can group has been fully loaded on the blank bottom panel as supported on the advancing bucket platform, the cam edges 41 of the wing cams 40 move into camming contact with the series of progressively elevated camming rollers 55 to thereby upswing the bucket side wings 34 into erect position. The end flanges 36 of the upswinging bucket wings move into overlapped relation to the end cans to positively assure accurate alignment of the can group on the blank bottom panel. With the upswinging movement of the bucket wings 34, the top flanges 37 thereof operate to infold the top panel sections *d* of the wrapper blank over the top end of the can group and the top panel sections *d* of the wrapper blank are so held until firmly connected together. The spaced pressure segments 34' on the inside face of the side wings 34 serve to press the adjacent blank side panel portions inwardly between adjacent cans to thereby assure tight wrapping of the blank, and additionally, to force the can chimes *c* into the chime receiving slits *e'* extending along the bottom and top horizontal edges of the blank side panels *b*.

When the wrapper blank is provided with handle sections *f*, the overhead handle folding blade 121 serves to upfold the handle sections *f* into paired relation during continuous travel of the bucket supported package. The belly section 121' of the upfolding blade extends between the two can rows during loading of the cans on the blank bottom panel *a* and during the interval that the bucket side wings 34 are in process of being upfolded and thus assists in preventing the bottom chimes *c'* of the cans *C* from becoming seated one on the other. The belly section 121' terminates before the bucket side wings 34 have been fully upfolded, and is thence replaced by the flat forwardly extending backing plate 124 extending at right angles to the forward upturning section 121" of the upfolding blade. The backing plate 124 provides support for the inturned blank top panel sections *d* as the handle sections *f* are being stapled together. When the handle sections *f* have been stapled together, the bucket side wings 34 are swung outwardly into horizontal position and the completed can package is withdrawn from the blade-like backing plate 124 as it advances for discharge.

Where a blank wrapper blank *A'*, whose top panel sections *d* are to be glued together in overlapped relation is to be used, the glue applying device 130 operates to apply two strips of adhesive *i* to one of the blank top panel sections *d* immediately after the can group has been loaded on the blank bottom panel, and preferably before the side panels *b* thereof have been upfolded. One of the series of bucket wing upfolding cam rollers 55 operates to infold the unglued top panel section *d* before the opposite glued top panel section *d* is infolded, as indicated in Fig. 26. Staggered infolding of the top panel sections *d*, with the glued section superimposed over the unglued section, is thus assured. The can package then continues to advance under the pressure belt 141 which operates to

press the overlapped blank top panel sections *d* into firm adhesive relation. The bucket side wings 34 are then unfolded and the completed can package ready for discharge.

As the can package supporting platforms 31 advance over the upper half section of the discharge sprocket 12, the package supporting platforms 31 are inclined to an increasing degree. The top surface of the bucket platforms 31 are sufficiently smooth to cause the can package supported thereon to slide forwardly and to discharge therefrom as soon as the can follower plate 32 of the preceding bucket platform 31 has assumed a substantially horizontal position as shown in Fig. 2. The discharging can package is then received by the bottom wall 152 of the can package trough 151 which in turn transfers the completed can package to the belt conveyor 157 for final removal to any desired location. The downwardly bent entry end of the bottom wall 152 is spaced a sufficient distance from the path of travel of the bottom platforms 31 to permit its can follower plates 32 to escape contact with the entry end of the receiving trough. Since the height of the can follower plates 32 is relatively low, the clearance distance between the advance edge of the supporting platform and the entry end of the receiving trough may be made sufficiently short so that the can package is fully supported on its inclined bucket platform until the front bottom edge of the can package has slid into supporting position on the bottom wall 152 of the receiving trough.

This improved can packaging apparatus operates automatically with a minimum of attention and can be operated to produce from eighty to one hundred twenty can packages per minute. The can feed lines 106 or 106' may be supplied directly from the canning machines, and the can packaging apparatus may be operated at an adjusted speed to take the entire output of a high speed canning machine. This packaging machine, using appropriately sized blanks, may be used to package a single line of cans in single line packages if desired. The apparatus requires a relatively small amount of floor space, is sturdy in construction, substantially fool-proof in operation, assures tight wrapping of the can groups, and is flexibly adapted to operate on various forms of can wrapping blanks and tightly wrap any number of cans in each can group either in a single row or in paired rows, as desired.

While certain novel features of this invention have been disclosed herein and are pointed out in the claims, it will be understood that various omissions, substitutions and changes may be made by those skilled in the art without departing from the spirit of this invention.

What is claimed is:

1. The method of enclosing a group of flat ended cylindrically bodied cans in erect position within a one-piece wrapper blank presenting a bottom panel, a pair of side panels and a pair of top panels, which includes, advancing the flat and unfolded wrapper blank, driving a row of erected cans diagonally and forwardly toward the advancing bottom panel, pushing the successive erect leading can diagonally across a side edge of the adjacent advancing bottom panel of the flat and unfolded wrapper blank until fully seated in erect position thereon, separating the end-most can of the can group prior to its placement on the rear portion of the advancing bottom panel from the following can to thereby insure deposition of the desired number of erect cans on the blank bottom panel, upfolding the blank side panels over the sides of the advancing can group, infolding the blank top panels over the upper end of the advancing can group, and connecting the blank top panels to complete the can package.

2. The method of enclosing a can group within a one-piece wrapper blank presenting a bottom panel, a pair of side panels and a pair of top panels which includes, advancing the wrapper blank, driving two rows of erected cans diagonally and forwardly in converging relation toward the bottom panel advancing therebetween, pushing the successive leading pair of cans diagonally across the

side edges of the adjacent advancing bottom panel until fully seated in erect position and in substantially abutting relation thereon, separating the end-most pair of cans of the can group prior to their placement on the rear portion

5 of the partly loaded bottom panel from the following pair of cans forming part of the following group to thereby insure deposition of the desired number of paired cans on the loaded bottom panel, upfolding the blank side panels over the sides of the advancing can group, infolding the blank top panels over the upper end of the advancing can group, and connecting the blank top panels to complete the can package.

3. The method of enclosing successive can groups with-in successive wrapper blanks each presenting a bottom panel, a pair of side panels and a pair of top panels, which includes, advancing successive wrapper blanks, driving a row of erected cans diagonally and forwardly toward the advancing bottom panels, pushing the successive leading can diagonally across a side edge of the adjacent advancing bottom panel until fully seated in erect position thereon, separating the end-most can of the can group prior to its placement on the rear portion of the partly loaded bottom panel from the following can forming part of the following group to thereby insure deposition of the desired number of cans on the loaded bottom panel, upfolding the blank side panels over the sides of the wrapper loaded can group, infolding the blank top panels over the upper end of the wrapper loaded can group, and connecting the blank top panels during advance of the enwrapped can group to complete the can package.

4. The method of enclosing successive can groups with-in successive wrapper blanks each presenting a bottom panel, a pair of side panels and a pair of top panels, which includes, advancing successive wrapper blanks at uniform speed, driving two rows of erected cans diagonally and forwardly in converging relation toward the blank bottom panel advancing therebetween, pushing the successive leading pair of cans diagonally across the side edges of the adjacent advancing bottom panel until fully seated in erect position and in substantially abutting relation thereon, separating the end-most pair of cans of the can group prior to their placement on the rear portion of the partly loaded bottom panel from the following pair of cans forming part of the following group to thereby insure deposition of the desired number of paired cans on the loaded bottom panel, upfolding the blank side panels over the sides of the advancing can group, infolding the blank top panels over the upper end of the advancing can group, and connecting the blank top panels during advance of the enwrapped can group to complete the can package.

5. The method of enclosing successive can groups with-in successive wrapper blanks each presenting a bottom panel, a pair of side panels, a pair of top panels and a pair of handle forming sections, which includes, advancing successive wrapper blanks at uniform speed, driving two rows of erected cans diagonally and forwardly in converging relation toward the blank bottom panel advancing therebetween, pushing the successive leading pair of cans diagonally across the side edges of the adjacent advancing blank bottom panel until fully seated in erect position and in substantially abutting relation thereon, separating the end-most pair of cans of the can group prior to their placement on the rear portion of the partly loaded bottom panel from the following pair of cans forming part of the following group to thereby insure deposition of the desired number of paired cans on the loaded bottom panel, upfolding the blank side panels over the sides of the advancing can group, infolding the blank top panels over the upper end of the advancing can group, facing the handle sections into abutting relation, and securing the handle sections together during advance of the wrapped can group to complete the can package.

6. The method of enclosing successive can groups with-in successive wrapper blanks each presenting a bottom

panel, a pair of side panels and a pair of top panels which includes, advancing successive wrapper blanks at uniform speed, driving two rows of erected cans diagonally and forwardly in converging relation toward the blank bottom panel advancing therebetween, pushing the successive leading pair of cans diagonally across the side edges of the adjacent advancing blank bottom panel until fully seated in erect position and in substantially abutting relation thereon, separating the end-most pair of cans of the can group prior to their placement on the rear portion of the partly loaded bottom panel from the following pair of cans forming part of the following group to thereby insure deposition of the desired number of paired cans on the loaded bottom panel, applying adhesive to one of said blank top panels, upfolding the blank side panels over the sides of the advancing can group, infolding the blank top panels in overlapped relation over the upper end of the advancing can group, and pressing the overlapped blank top panels into secured relation during advance of the enwrapped can group to complete the can package.

7. Apparatus for enclosing successive can groups within successive wrapper blanks each having a bottom panel, a pair of side panels, a pair of top panels and a pair of handle sections which includes, a conveyor formed by a series of hingedly connected blank supporting platforms, means for advancing said platforms, means for successively depositing a flat wrapper blank on the successively advancing platforms, means for depositing successive can groups on the blank bottom panels as the platform supported blanks are progressively advanced, means for upfolding the paired blank side panels over the sides of the successive can groups during advance thereof, means for infolding the paired top panels over the top ends of the successive can groups during advance thereof, means for upfolding the paired handle sections during advance thereof, means for connecting the upfolded handle sections during advance of the successive blank enwrapped cans to complete the can package, and means for operating said blank depositing means, can group depositing means, blank side panel upfolding means, blank top panel infolding means and handle section connecting means in synchronism with the advance movement of said conveyor platforms.

8. Apparatus for enclosing successive can groups within successive wrapper blanks each having a bottom panel, a pair of side panels and a pair of top panels which includes, a conveyor formed by a series of hingedly connected blank supporting platforms, means for advancing said platforms, means for successively depositing a flat wrapper blank on the successively advancing platforms, means for driving and guiding two rows of erected cans diagonally and forwardly in converging relation towards the successively advancing blank bottom panels and into paired seated position and into aligned and twin columnar relation on each bottom panel as the platform supported blanks are progressively advanced, means for applying adhesive to one of said paired top panels during advance thereof, means for upfolding the blank side panels over the sides of the successively seated can groups during advance thereof, means for infolding the paired top panels into overlapped relation over the top ends of the successive can groups during advance thereof, means for pressing the infolded top panels into adhered relation during advance of the successive blank wrapped cans to complete the can package, and means for operating said blank depositing means, can group driving means, adhesive applying means, blank side panel upfolding means, blank top panel infolding means and top panel pressing means in synchronism with the advance movement of said conveyor platforms.

9. Apparatus for wrapping can groups within one-piece wrapper blanks each presenting a bottom panel, a pair of side panels and a pair of top panels which includes, an endless conveyor formed by a series of hingedly con-

nected blank supporting platforms, means for advancing said conveyor platforms at uniform speed, mechanism for feeding and depositing successive flat wrapper blanks onto the successive advancing platforms of said conveyor, means for separating the cans into groups, means for driving and guiding a columnar group of erected cans diagonally and forwardly toward the blank bottom panel and into longitudinally aligned seated position on each of the blank bottom panels as the platform supported blanks are progressively advanced, means for upfolding the blank side panels over the sides of the seated can groups during progressive advance thereof, means for infolding the blank top panels over the top end of the blank contained can group during progressive advance thereof, and means for connecting the infolded top panels to complete the can packages during progressive advance of the blank wrapped can groups.

10. Apparatus for wrapping can groups within one-piece wrapper blanks each presenting a bottom panel, 20 a pair of side panels and a pair of top panels which includes, an endless conveyor formed by a series of hingedly connected blank supporting platforms, means for advancing said conveyor platforms at uniform speed, mechanism for feeding and depositing successive flat wrapper 25 blanks onto the successive advancing platforms of said conveyor, a can separator member projecting upwardly between the adjacent ends of said blank supporting platforms for separating the cans into groups, means for driving two columnar rows of erected cans diagonally and forwardly in converging relation towards the successive bottom panels of the blanks advancing therebetween, means for guiding the driven cans into paired seated 30 position and twin columnar relation onto each of the blank bottom panels as the platform supported blanks are progressively advanced, means for upfolding the blank side panels over the sides of the seated can groups during progressive advance thereof, means for infolding the blank top panels over the top end of the blank contained can group during progressive advance thereof, and 35 means for connecting the infolded top panels to complete the can packages during progressive advance of the blank wrapped can groups.

11. Apparatus for enclosing can groups within wrapper 40 blanks each having a bottom panel and a pair of side panels, said apparatus including, a continuous conveyor formed by a series of hingedly connected blank supported buckets, each of said buckets including a bottom platform having a blank supporting face whose area is approximately equal to the blank bottom panel, and blank side panel supporting wings hingedly connected to the opposite side edges of the bottom platform, means for advancing said bucket conveyor, means for depositing successive wrapper blanks within the advancing buckets, means for supporting the bucket wings in extended position during placement of the wrapped blanks therein, means for depositing successive can groups on the platform supported bottom panels during advance movement thereof, and means for upfolding said bucket wings to thereby upfold the blank side panels during advance movement thereof.

12. Apparatus for enclosing can groups within wrapper 45 blanks each having a bottom panel, a pair of side panels and a pair of top panels, said apparatus including, a continuous conveyor formed by a series of hingedly connected blank supported buckets, each of said buckets including a bottom platform having a blank supporting face whose area is approximately equal to the blank bottom panel, and blank side panel supporting wings hingedly connected to the opposite side edges of the bottom platform, each of said bucket wings having a pair of can aligning end flanges extending from the end edges thereof and a top panel infolding flange extending inwardly from the top edge thereof, means for advancing said bucket conveyor, means for depositing successive 50 wrapper blanks within the advancing buckets, means for

Supporting the bucket wings in extended position during placement of the wrapper blanks therein, means for depositing successive can groups on the platform supported bottom panels during advance movement thereof, and means for upfolding said bucket wings to thereby upfold the side panels and infold the top panels of the can group containing blanks during advance movement thereof.

13. Apparatus for enclosing can groups within wrapper blanks each having a bottom panel, a pair of side panels and a pair of top panels, said apparatus including, a continuous conveyor formed by a series of hingedly connected blank supported buckets, each of said buckets including a bottom platform having a blank supporting face whose area is approximately equal to the blank bottom panel and blank side panel supporting wings hingedly connected to the opposite side edges of the bottom platform, each of said bucket wings having a pair of can aligning end flanges extending from the end edges thereof, a top panel infolding flange extending inwardly from the top edge thereof, and spaced side panel pressure segments on the inside face of each of said wings, means for advancing said bucket conveyor, means for depositing successive wrapper blanks within the advancing buckets, means for supporting the bucket wings in extended position during placement of the wrapper blanks therein, means for depositing successive can groups on the platform supported bottom panels during advance movement thereof, and means for upfolding said bucket wings to thereby upfold the blank side panels, infold the blank top panels and enclose the can group therein during advance movement thereof.

14. Apparatus for enclosing can groups within wrapper blanks each having a bottom panel, a pair of side panels and a pair of top panels, said apparatus including, a continuous conveyor formed by a series of hingedly connected blank supported buckets, each of said buckets including a bottom platform having a blank supporting face whose area is approximately equal to the blank bottom panel, a cam follower plate extending at substantially a right angle from the blank supporting face of said bottom platform, and blank side panel supporting wings hingedly connected to the opposite side edges of the bottom platform, each of said bucket wings having a pair of can aligning end flanges extending from the end edges thereof and a top panel infolding flange extending inwardly from the top edge thereof, means for advancing said bucket conveyor, means for depositing successive wrapper blanks within the advancing buckets, means for supporting the bucket side wings in extended position during placement of the wrapper blanks therein, means for depositing successive can groups on the platform supported bottom panels during advance movement thereof, and means for upfolding said bucket wings to thereby upfold the blank side panels, infold the blank top panels and enclose the can group therein during advance movement thereof.

15. Apparatus for enclosing can groups within wrapper blanks each having a bottom panel, a pair of side panels and a pair of top panels, said apparatus including, a continuous conveyor formed by a series of blank supported buckets, each of said buckets including a bottom platform having a blank supporting face whose area is approximately equal to the blank bottom panel, a can follower plate extending at substantially a right angle from the blank supporting face of said bottom platform, a pair of supporting rollers mounted on the opposite face of said platform and positioned adjacent one end thereof, coupling means for hingedly connecting the adjacent platforms, and blank side panel supporting wings hingedly connected to the opposite side edges of the bottom platform, each of said bucket wings having a pair of can aligning end flanges extending from the end edges thereof and a top panel infolding flange extending inwardly from the top edge thereof, means for advancing said bucket conveyor, means for depositing successive wrapper blanks

within the advancing buckets, means for supporting the bucket wings in extended position during placement of the wrapper blanks therein, means for depositing successive can groups on the platform supported bottom panels during advance movement thereof, and means for upfolding said bucket wings to thereby upfold the blank side panels, infold the blank top panels and enclose the can group therein during advance movement thereof.

16. Apparatus for enclosing can groups within wrapper blanks each having a bottom panel, a pair of side panels and a pair of top panels, said apparatus including, a continuous conveyor formed by a series of hingedly connected blank supporting buckets, each of said buckets including a bottom platform having a flat supporting face whose area is substantially equal to the blank bottom panel to be supported thereon, a can follower plate extending at substantially a right angle from an end edge of said bottom platform, and blank side panel upfolding wings hingedly connected to the opposite side edges of the bottom platform, each of said bucket side wings having a pair of can aligning end flanges extending inwardly from the end edges thereof and a top panel infolding flange extending inwardly from the top edge thereof, means for advancing said bucket conveyor, means for depositing successive wrapper blanks within the advancing buckets, means for supporting the bucket wings in extended position during placement of the wrapper blanks therein, means for depositing successive can groups on the platform supported blank bottom panels during advance movement thereof, and means for upfolding said bucket wings to thereby upfold the blank side panels and infold the paired top panels during advance movement thereof.

17. Apparatus for enclosing can groups within wrapper blanks each having a bottom panel, a pair of side panels and a pair of top panels, said apparatus including, a continuous conveyor formed by a series of hingedly connected blank supporting buckets, each of said buckets including a bottom platform having a flat supporting face whose area is substantially equal to the blank bottom panel to be supported thereon, a can follower plate extending at substantially a right angle from an end edge of said bottom platform, and blank side panel upfolding wings hingedly connected to the opposite side edges of the bottom platform, each of said bucket side wings having a pair of can aligning end flanges extending inwardly from the end edges thereof and a top panel infolding flange extending inwardly from the top edge thereof, and spaced pressure segments on the inside face of each of said side wings adjacent the inner face of the top flange thereof, means for advancing said bucket conveyor, means for depositing successive wrapper blanks within the advancing buckets, means for supporting the bucket wings in extended position during placement of the wrapper blanks therein, means for depositing successive can groups on the platform supported panels during advance movement thereof, and means for upfolding said bucket wings to thereby upfold the blank side panels and infold the paired top panels during advance movement thereof.

18. A can wrapping bucket operative to enclose a can group within a wrapper blank having a bottom panel, a pair of side panels and a pair of top panels, said bucket including, a bottom platform having a flat supporting face whose area is substantially equal to the blank bottom panel to be supported thereon, a can follower plate extending at substantially a right angle from an end edge of said bottom platform, axle supporting elements projecting from the opposite face of said platform and positioned adjacent one end thereof, a transverse axle having the ends thereof projecting through said axle supporting elements and having a roller mounted on each end thereof, coupling means at the other end of the platform for hingedly connecting the platform to an adjacent platform, and side panel upfolding wings hingedly connected to the opposite side edges of the bottom platform, each of said

bucket wings having a pair of can aligning end flanges extending inwardly from the end edges thereof and a top panel infolding flange extending inwardly from the top edge thereof.

19. Can packaging apparatus including, a continuous conveyor formed by a series of hingedly connected blank supporting platforms, means for advancing said conveyor platforms, means for depositing a wrapper blank on successive platforms, loading mechanism operative to deposit successive cans in upright position on the platform supported wrapper blanks during continuous advance thereof, said mechanism including a can driving rotor on one side of the line of travel of the blank supporting platforms, a table plate having a can entry section and a can exit section fixedly supported in the plane of the can driving rotor and in surrounding relation thereto, a can entry chute extending over said entry section for guiding a line of erect cans over said entry section and into driving engagement with said rotor, a can exit chute extending diagonally and forwardly over the can exit section and thence longitudinally beyond the discharge edge of the can exit section whereby successive lead cans driven by said rotor are guided in erect seated position and columnar alignment onto the advancing platform supported wrapper blank, and means for rotating said can driving rotors at a peripheral speed approximating the speed of advance of the successive blank supporting platforms.

20. Can packaging apparatus including, a continuous conveyor formed by a series of hingedly connected blank supporting platforms, means for advancing said conveyor platforms, means for depositing a wrapper blank on successive platforms, can loading mechanism operative to deposit successive cans in upright position on the platform supported wrapper blanks during continuous advance thereof, said mechanism including a can driving rotor on each side of the line of travel of the blank supporting platforms, a table plate having a can entry section and a can exit section fixedly supported in the plane of each can driving rotor and in surrounding relation thereto, a can entry chute extending over each entry section for guiding a line of erect cans over the entry section and into driving engagement with the adjacent rotor, a can exit chute extending diagonally and forwardly over each can exit section, said can exit chutes extending in converging relation adjacent the discharge edges of said exit sections and having supplemental guide means extending longitudinally in the direction of advance of said platform and beyond said exit sections, said converging can exit chutes and supplemental guide means being operative to direct the successive lead cans as driven by said rotors in erect seated position and in twin columnar alignment onto the advancing platform supported wrapper blank, and means for rotating said can driving rotors at a peripheral speed approximating the speed of advance of the successive blank supporting platforms.

21. Can packing apparatus including, a continuous conveyor formed by a series of hingedly connected blank supporting platforms, means for advancing said conveyor platforms, means for depositing a wrapper blank on successive platforms, can loading mechanism operative to deposit successive cans in upright position on the platform supported wrapper blanks during continuous advance thereof, said mechanism including a can driving rotor on each side of the line of travel of the blank supporting platforms, a table plate having a can entry section and a can exit section fixedly supported in the plane of each can driving rotor and in surrounding relation thereto, a can entry chute extending over each entry section for guiding a line of erect cans over the entry section and into driving engagement with the adjacent rotor, a can exit chute extending diagonally and forwardly over each can exit section, said chutes presenting a pair of inner can guiding walls converging together in a forwardly extending V formation over the approximate

center line of the advancing blank supporting platform and a pair of outer can guide walls extending substantially parallel to said inner walls for guiding the erect cans as driven by said rotors across the opposite side edges of the advancing blank supporting platforms, and means for rotating said can driving rotors at a peripheral speed approximating the speed of advance of the successive blank supporting platforms.

22. Can packaging apparatus including, a continuous conveyor formed by a series of hingedly connected blank supporting platforms, means for advancing said conveyor platforms, means for depositing a wrapper blank on successive platforms, can grouping and loading mechanism operative to deposit successive can groups in upright position on the platform supported wrapper blanks during continuous advance thereof, said mechanism including a can driving rotor on each side of the line of travel of the blank supporting platforms, can separator plates extending transversely between adjacent platforms and advancing with said conveyor platforms, a table plate having a can entry section and a can exit section fixedly supported in the plane of each can driving rotor and in surrounding relation thereto, said exit sections presenting parallel can discharge edges positioned slightly above but closely adjacent to the opposite side edges of the advancing platforms, a can entry chute extending over each entry section for guiding a line of erect cans over the entry section and into driving engagement with the adjacent rotor, a can exit chute extending diagonally and forwardly over each can exit section, said can exit chutes extending in converging relation adjacent the discharge edges of said exit sections and having supplemental guide means extending longitudinally in the direction of the advance of said platforms and beyond the discharge edges of said exit sections, said converging can exit chutes and supplemental guide means being operative to direct successive lead cans as driven by said rotors in erect seated position and in twin columnar alignment onto the advancing platform supported wrapper blank, and means for rotating said can driving rotors at a peripheral speed approximating the speed of advance of the successive blank supporting platforms.

23. Can packaging apparatus including, a continuous conveyor formed by a series of hingedly connected blank supporting platforms, means for advancing said conveyor platforms, means for depositing a wrapper blank on successive platforms, can grouping and loading mechanism operative to deposit successive can groups in upright position on the platform supported wrapper blanks during continuous advance thereof, said mechanism including a can driving rotor on each side of the line of travel of the blank supporting platforms, can separator plates extending between adjacent platforms and advancing with said conveyor platforms, a table plate having a can entry section and a can exit section fixedly supported in the plane of each can driving rotor and in surrounding relation thereto, said exit sections presenting parallel can discharge edges positioned slightly above but closely adjacent to the opposite side edges of the advancing platforms, a can entry chute extending over each entry section for guiding a line of erect cans over the entry section and into driving engagement with the adjacent rotor, a can exit chute extending diagonally and forwardly over each can exit section, and means for rotating said can driving rotors at a peripheral speed approximating the speed of advance of the successive blank supporting platforms, said can separator plates being operative to knife between the end-most pair of cans prior to their placement on the rear portion of the partly loaded wrapper blank and the following pair of cans.

24. Can packaging apparatus including, a continuous conveyor formed by a series of hingedly connected blank supporting platforms, means for advancing said conveyor platforms, means for depositing a wrapper blank on successive platforms, can loading mechanism operative to deposit successive cans in upright position on the platform

supported wrapper blanks during continuous advance thereof, said mechanism including a can driving rotor on each side of the line of travel of the blank supporting platforms, a table plate having a can entry section and a can exit section fixedly supported in the plane of each can driving rotor and in surrounding relation thereto, said exit sections presenting parallel can discharge edges positioned slightly above but closely adjacent to the opposite side edges of the advancing platforms, a can entry chute extending over each entry section for guiding a line of erect cans over the entry section and into driving engagement with the adjacent rotor, a can exit chute extending diagonally and forwardly over each can exit section, said exit chutes presenting a pair of inner can guiding walls converging together in a forwardly extending V formation over the approximate center line of the advancing blank supporting platforms, and a pair of outer can guiding walls extending substantially parallel to said inner walls for guiding the erect cans as driven by said rotor across the opposite side edges of the adjacent advancing blank supporting platforms, and means for rotating said can driving rotors at a peripheral speed approximately the speed of advance of the successive blank supporting platforms.

25. Can packaging apparatus including, a continuous conveyor formed by a series of hingedly connected blank supporting platforms, means for advancing said conveyor platforms, means for depositing a wrapper blank on successive platforms, can grouping and loading mechanism operative to deposit successive can groups in upright position on the platform supported wrapper blanks during continuous advance thereof, said mechanism including a can driving rotor on each side of the line of travel of the blank supporting platforms, can separator plates extending between adjacent platforms and advancing with said conveyor platforms, a table plate having a can entry section and a can exit section fixedly supported in the plane of each can driving rotor and in surrounding relation thereto, said exit sections presenting parallel can discharge edges positioned slightly above but closely adjacent to the opposite side edges of the advancing platforms, a can entry chute extending over each entry section for guiding a line of erect cans over the entry section and into driving engagement with the adjacent rotor, a can exit chute extending diagonally and forwardly over each can exit section, said exit chutes presenting a pair of inner can guiding walls converging together in a forwardly extending V formation over the approximate center line of the advancing blank supporting platforms, and a pair of outer can guiding walls extending substantially parallel to said inner walls for guiding the erect cans as driven by said rotors across the opposite side edges of the adjacent advancing blank supporting platforms, said can separator plates being operative to knife between the end-most pair of cans prior to their placement on the rear portion of the partly loaded wrapper blank and the following pair of cans.

26. Can packaging apparatus including, a continuous conveyor formed by a series of hingedly connected blank supporting platforms, means for advancing said conveyor platforms, means for depositing a wrapper blank on successive platforms, can loading mechanism operative to deposit successive cans in upright position on the platform supported wrapper blanks during continuous advance thereof, said mechanism including a can driving rotor on one side of the line of travel of the blank supporting platforms, said can driving rotor including a rotatably mounted can platform, a pair of spaced discs mounted centrally on said rotatable platform and in spaced relation thereto and presenting aligned can receiving cells formed in the peripheries of said discs, a table plate having a can entry section and a can exit section fixedly supported in the plane of the rotor platform and in surrounding relation thereto, a can entry chute extending over said entry section for guiding a line of erect cans over said entry sec-

tion and into the successive can receiving cells of said rotor, a can exit chute extending diagonally and forwardly over the can exit section for guiding the erect cans as driven by said rotor diagonally across the adjacent side edge of the advancing blank supporting platforms, and means for rotating said can driving rotors at a peripheral speed approximating the speed of advance of the successive blank supporting platforms.

27. Can packaging apparatus including, a continuous conveyor formed by a series of hingedly connected blank supporting platforms, means for advancing said conveyor platforms, means for depositing a wrapper blank on successive platforms, can loading mechanism operative to deposit successive cans in upright position on the platform supported wrapper blanks during continuous advance thereof, said mechanism including a can driving rotor on each side of the line of travel of the blank supporting platforms, each of said can driving rotors including a rotatably mounted can platform, a pair of spaced discs mounted centrally on said rotatable platform and in spaced relation thereto and presenting aligned can receiving cells formed in the peripheries of said discs, a table plate having a can entry section and a can exit section fixedly supported in the plane of each rotor platform and in surrounding relation thereto, a pair of can entry chutes extending over said entry sections for guiding two lines of erect cans over said entry sections and into the successive can receiving cells of adjacent rotors, a pair of can exit chutes extending diagonally and forwardly over the can exit sections and converging over the path of travel of said platforms for guiding the two rows of cans as driven by said rotors diagonally across the opposite side edges of the advancing blank supporting platforms, and means for rotating said can driving rotors at a peripheral speed approximating the speed of advance of the successive blank supporting platforms.

28. Apparatus for enclosing successive can groups within successive wrapper blanks each having a bottom panel, a pair of side panels and a pair of top panels, said apparatus including, a conveyor presenting a series of hingedly connected blank supporting platforms, means for driving said conveyor, means for successively depositing the bottom panel of the successive flat and unfolded wrapper blanks in registered seating position on the successive advancing platforms, means for guiding and driving successive columnar groups of erected cans diagonally toward the advancing blank bottom panel and into erect seated position on the successive blank bottom panels of the flat and unfolded wrapper blanks and into longitudinally aligned relation with respect to the direction of travel of the flat and unfolded platform supported blanks, means for upfolding the blank side panels over the opposite sides of the successive groups of erect and blank seated cans during advance thereof, means for infolding the paired top panels of the blanks over the top ends of the successive can groups during the advance thereof, and means for connecting the infolding top panels during advance of the successive blank wrapped cans to complete the can packages.

29. Apparatus for enclosing successive can groups within successive wrapper blanks each having a bottom panel, a pair of side panels and a pair of top panels, said apparatus including, a conveyor presenting a series of hingedly connected blank supporting platforms, means for driving said conveyor, means for successively depositing the bottom panels of successive flat and unfolded wrapper blanks in registered seating position on the successive advancing platforms, means for guiding and driving successive columnar groups of erected cans diagonally toward the advancing blank bottom panel and into erect seated position on the successive blank bottom panels of the flat and unfolded wrapper blanks and into longitudinally aligned relation with respect to the direction of travel of the flat and unfolded platform supported blanks, means for upfolding the blank side panels over the top ends of the successive can groups during the advance thereof, and means for connecting the infolding top panels during advance of the successive blank wrapped cans to complete the can packages.

posite sides of the successive groups of erect and blank seated cans during advance thereof, means for infolding the paired top panels of the blanks over the top ends of the successive can groups during the advance thereof, and means for operating said blank depositing means, can group driving means, blank side panel upfolding means and blank top panel infolding means in synchronism with the advance movement of said conveyor platforms.

30. Apparatus for enclosing successive can groups within successive wrapper blanks each having a bottom panel, a pair of side panels and a pair of top panels, said apparatus including, a conveyor having a series of hingedly connected blank supporting platforms, means for driving said conveyor, means for successively depositing the bottom panels of successive flat and unfolded wrapper blanks in registered seating position on the successive advancing platforms, means for guiding and driving successive columnar groups of erected cans diagonally toward the advancing blank bottom panel and into erect seated position on the successive blank bottom panels of the flat and unfolded wrapper blanks and into longitudinally aligned relation with respect to the direction of travel of the flat and unfolded platform supported blanks, means for upfolding the paired blank side panels over the opposite sides of the successive groups of erect and blank seated cans during advance thereof, means for infolding the paired top panels of the blanks over the top ends of the successive can groups during the advance thereof, means for connecting the infolding top panels during advance of the successive blank wrapped cans to complete the can packages, and means for operating said blank depositing means, can group driving means, blank side panel upfolding means, blank top panel infolding means, and top panel connecting means in synchronism with the advance movement of said conveyor platforms.

31. Apparatus for enclosing successive can groups within successive wrapper blanks each having a bottom panel, a pair of side panels, a pair of top panels and a pair of handle sections which includes, a conveyor formed by a series of hingedly connected blank supporting platforms, means for advancing said platforms, means for successively depositing a flat and unfolded wrapper blank on the successively advancing platforms, means for depositing successive can groups in erect seated position on the blank bottom panels of the flat and unfolded wrapper blanks as the platform supported blanks are progressively advanced, means for upfolding the paired blank side panels over the sides of the successive can groups during advance thereof, means for infolding the paired top panels over the top ends of the successive erect can groups during advance thereof, and means for operating said blank depositing means, can group depositing means, blank side panel upfolding means, blank top panel infolding means in synchronism with the advance movement of said conveyor platforms.

32. Apparatus for enclosing successive can groups within successive wrapper blanks each having a bottom panel, a pair of side panels and a pair of top panels which includes, a conveyor formed by a series of hingedly connected blank supporting platforms, means for advancing said platforms, means for successively depositing a flat and unfolded wrapper blank on the successively advancing platforms, means for driving and guiding two rows of erected cans diagonally and forwardly in converging relation towards the successively advancing blank bottom panels and into paired and upright seated position and into aligned and twin columnar relation on each bottom panel of the flat and unfolded wrapper blanks as the platform supported blanks are progressively advanced, means for upfolding the blank side panels over the sides of the successively seated can groups during advance thereof, and means for infolding the paired top panels 75

into overlapped relation over the top ends of the successive can groups during advance thereof.

33. Apparatus for enclosing successive can groups within successive wrapper blanks each having a bottom panel, 5 a pair of side panels and a pair of top panels which includes, a conveyor formed by a series of hingedly connected blank supporting platforms, means for advancing said platforms, means for successively depositing a flat and unfolded wrapper blank on the successively advancing platforms, means for driving and guiding two rows of erected cans diagonally and forwardly in converging relation towards the successively advancing blank bottom panels and into paired and upright seated position and into aligned and twin columnar relation on each bottom panel of the flat and unfolded wrapper blanks as the platform supported blanks are progressively advanced, means for upfolding the blank side panels over the sides of the successively seated can groups during advance thereof, means for infolding the paired top panels into overlapped relation over the top end of the successive can groups during advance thereof, and means for pressing the infolded top panels into bonded relation during advance of the successive blank enwrapped cans to complete the can package.

34. Apparatus for enclosing successive can groups within successive wrapper blanks each having a bottom panel, a pair of side panels and a pair of top panels which includes, a conveyor formed by a series of hingedly connected blank supporting platforms, means for advancing said platforms, means for successively depositing a flat and unfolded wrapper blank on the successively advancing platforms, means for driving and guiding two rows of erected cans diagonally and forwardly in converging relation towards the successively advancing blank bottom panels and into paired and upright seated position and into aligned and twin columnar relation on each bottom panel of the flat and unfolded wrapper blanks as the platform supported blanks are progressively advanced, means for upfolding the blank side panels over the sides of the successively seated can groups during advance thereof, and means for operating said blank depositing means, can group driving means, blank side panel upfolding means and blank top panel infolding means in synchronism with the advance movement of said conveyor platforms.

35. Apparatus for enclosing successive can groups within successive wrapper blanks each having a bottom panel, 50 a pair of side panels and a pair of top panels which includes, a conveyor formed by a series of hingedly connected blank supporting platforms, means for advancing said platforms, means for successively depositing a flat and unfolded wrapper blank on the successively advancing platforms, means for driving and guiding two rows of erected cans diagonally and forwardly in converging relation towards the successively advancing blank bottom panels and into paired and upright seated position and into aligned and twin columnar relation on each bottom panel of the flat and unfolded wrapper blanks as the platform supported blanks are progressively advanced, means for upfolding the blank side panels over the sides of the successively seated can groups during advance thereof, means for infolding the paired top panels into overlapped relation over the top ends of the successive can groups during advance thereof, means for pressing the infolded top panels into bonded relation during advance of the successive blank enwrapped cans to complete the can package, and means for operating said blank depositing means, can group driving means, blank side panel upfolding means and blank top panel infolding means in synchronism with the advance movement of said conveyor platforms.

36. Can packaging apparatus including, a continuous conveyor formed by a series of hingedly connected blank

supporting platforms, means for advancing said conveyor platforms, means for depositing a wrapper blank on successive platforms, loading mechanism operative to deposit successive cans in upright position on the flat and unfolded platform supported wrapper blanks during continuous advance thereof, said mechanism including a can driving rotor on one side of the line of travel of the blank supporting platforms, a table plate having a can entry section and a can exit section fixed in can supporting relation to the can driving rotor, a can entry chute extending over said entry section for guiding a line of erect cans over said entry section and into driving engagement with said rotor, a can exit chute extending diagonally and forwardly over the can exit section whereby successive cans driven by said rotor are guided in erect seated position onto the advancing platform supported wrapper blank, and means for rotating said can driving rotor at a peripheral speed approximating the speed of advance of the successive blank supporting platforms.

37. Can packaging apparatus including, a continuous conveyor formed by a series of hingedly connected blank supporting platforms, means for advancing said conveyor platforms, means for depositing a wrapper blank on successive platforms, can loading mechanism operative to deposit successive cans in upright position on the flat and unfolded platform supported wrapper blanks during continuous advance thereof, said mechanism including a can driving rotor on each side of the line of travel of the blank supporting platforms, a table plate having a can entry section and a can exit section fixed in can supporting relation to each can driving rotor, a can entry chute extending over each entry section for guiding a line of erect cans over the entry section and into driving engagement with the adjacent rotor, can exit chutes extending diagonally and forwardly over said can exit sections and presenting can guiding walls for guiding the erect cans as driven by said rotors across the opposite side edges of the advancing blank supporting platforms, and means for rotating said can driving rotors at a peripheral speed approximating the speed of advance of the successive blank supporting platforms.

38. Can packaging apparatus including, a continuous conveyor formed by a series of hingedly connected blank supporting platforms, means for advancing said conveyor platforms, means for depositing a wrapper blank on successive platforms, can groupings and loading mechanism operative to deposit successive can groups in upright position on the flat and unfolded platform supported wrapper blanks during continuous advance thereof, said mechanism including a can driving rotor on each side of the line of travel of the blank supporting platforms, can separator plates extending transversely between adjacent platforms and advancing with said conveyor platforms, a table plate having a can entry section and a can exit section fixed in can supporting relation to each can driving rotor, said exit sections presenting parallel can discharge edges positioned slightly above but closely adjacent to the opposite side edges of the advancing platforms, a can entry chute extending over each entry section for guiding a line of erect cans over the entry section and into driving engagement with the adjacent rotor, a can exit chute extending diagonally and forwardly over each can exit section operative to direct successive lead cans as driven by said rotors in erect seated position and in twin columnar alignment onto the advancing platform supported wrapper blank, and means for rotating said can driving rotors at a peripheral speed approximating the speed of advance of the successive blank supporting platforms.

39. Can packaging apparatus including, a continuous conveyor formed by a series of hingedly connected blank supporting platforms, means for advancing said conveyor platforms, means for depositing a wrapper blank on successive platforms, can grouping and loading mechanism operative to deposit successive can groups in upright posi-

tion on the flat and unfolded platform supported wrapper blanks during continuous advance thereof, said mechanism including a can driving rotor on each side of the line of travel of the blank supporting platforms, can separator plates extending between adjacent platforms and advancing with said conveyor platforms, a table plate having a can entry section and a can exit section fixed in can supporting relation to each can driving rotor, said exit sections presenting parallel can discharge edges positioned slightly above but closely adjacent to the opposite side edges of the advancing platforms, a can entry chute extending over each entry section for guiding a line of erect cans over the entry section and into driving engagement with the adjacent rotor, a can exit chute extending diagonally and forwardly over each can exit section, and means for rotating said can driving rotors at a peripheral speed approximating the speed of advance of the successive blank supporting platforms, said can separator plates being operative to separate the end-most pair of cans prior to their placement on the rear portion of the partly loaded wrapper blank from the following pair of cans.

40. Apparatus for enclosing can groups within wrapper blanks presenting a bottom panel, a pair of side panels, and a pair of top panels which includes, a continuous conveyor formed by a series of hingedly connected blank supporting platforms each having a can follower plate projecting from the rear end thereof, rotatable conveyor supporting members at the head and discharge ends of the apparatus, means for driving said conveyor to advance the platforms, means for depositing successive flat and unfolded blanks on the successively advancing platforms with the bottom panels thereof in registered seating position on the platforms, means for depositing can groups in erect position on the platform supported bottom panels of the flat and unfolded wrapper blanks, means for upfolding the paired side panels of the wrapper blanks over the opposite sides of the erect can groups, means for infolding the paired top panels of the can enclosing blanks in overlying relation to the top ends of the erect can groups, means for operating said blank depositing means, can group depositing means, blank side panel unfolding means and blank top panel infolding means in synchronism with the advance movement of said platforms toward the discharge end of said conveyor, and a can package receiving chute adjacent the discharge end of the conveyor for receiving the can packages as they are ejected from their supporting platforms.

41. Apparatus for enclosing can groups within wrapper blanks presenting a bottom panel, a pair of side panels, and a pair of top panels which includes, a continuous conveyor formed by a series of hingedly connected blank supporting platforms each having a can follower plate projecting from the rear end thereof, rotatable conveyor supporting members at the head and discharge ends of the apparatus, means for driving said conveyor to advance the platforms, means for depositing successive flat and unfolded wrapper blanks on the successively advancing platforms with the bottom panels thereof in registered seating position on said platforms, means for depositing can groups in erect position on the platform supported bottom panels of the flat and unfolded wrapper blanks, means for upfolding the paired side panels of the wrapper blanks over the opposite sides of the erect can groups, means for infolding the top panels of the can enclosing blanks in overlying relation to the top ends of the erect can groups, means for operating said blank depositing means, can group depositing means, blank side panel upfolding means, and blank top panel infolding means in synchronism with the advance movement of said platforms toward the discharge end of said conveyor, and a downwardly inclined can package receiving chute positioned below the horizontal path of travel of said platforms and adjacent the discharge end of the conveyor for receiving the completed can packages as they slide forwardly from their supporting platforms during the

downwardly inclined travel of the supporting platforms at the discharge end of the conveyor, the upper can receiving edge of said package receiving chute being spaced a sufficient distance from the discharge end of the conveyor to permit unobstructed movement of the can follower plates therebetween.

42. The method of enclosing successive can groups within successive wrapper blanks each presenting a bottom panel, a pair of side panels and a pair of top panels which includes, advancing successive flat and unfolded wrapper blanks in a direction parallel to the longitudinal axis of its bottom panel, driving two rows of erected cans diagonally and forwardly in converging relation toward the blank bottom panel advancing therebetween, pushing the successive leading pair of cans diagonally across the side edges of the adjacent advancing blank bottom panel until fully seated in erect position on the advancing bottom panel of the flat and unfolded wrapper blanks to thereby provide two rows of bottom panel seated cans longitudinally aligned in the direction of blank travel, separating the end-most pair of cans of the can group prior to their placement on the rear portion of the partly loaded bottom panel from the following pair of cans forming part of the following group to thereby insure deposition of the desired number of paired cans on the loaded bottom panel, upfolding the blank side panels over the sides of the advancing can group, and infolding the paired blank top panels in overlapped relation over the upper end of the can group during advance thereof.

43. The method of enclosing successive can groups within successive wrapper blanks each presenting a bottom panel, a pair of side panels and a pair of top panels which includes, advancing successive flat and unfolded wrapper blanks at uniform speed in a direction parallel to the longitudinal axis of its bottom panel, driving two rows of erected cans diagonally and forwardly in converging relation toward the blank bottom panel advancing therebetween, guiding and pushing the successive leading pair of cans diagonally across the side edges of the adjacent advancing blank bottom panel until fully seated in erect position and in abutting relation on the advancing bottom panel of the flat and unfolded wrapper blanks to thereby provide two rows of bottom panel seated cans longitudinally aligned in the direction of blank travel, separating the end-most pair of cans of the can group prior to their placement on the rear portion of the partly loaded bottom panel from the following pair of cans forming part of the following group to thereby insure deposition of the desired number of paired cans on the loaded bottom panel, upfolding the blank side panels over the sides of the advancing can group, and infolding the paired blank top panels in overlapped relation over the upper end of the can group during advance thereof.

44. The method of enclosing successive can groups within successive wrapper blanks each presenting a bottom panel, a pair of side panels and a pair of top panels which includes, advancing successive flat and unfolded wrapper blanks in a direction parallel to the longitudinal axis of its bottom panel, driving two rows of erected cans diagonally and forwardly in converging relation toward the blank bottom panel advancing therebetween, pushing the successive leading pair of cans diagonally across the side edges of the adjacent advancing blank bottom panel until fully seated in erect position on the advancing bottom panel of the flat and unfolded wrapper blanks to thereby provide two rows of bottom panel seated cans longitudinally aligned in the direction of blank travel, separating the end-most pair of cans of the can group prior to their placement on the rear portion of the partly loaded bottom panel from the following pair of cans forming part of the following group to thereby insure deposition of the desired number of paired cans on the loaded bottom panel, upfolding the blank side panels over the sides of the advancing can group, infolding the

paired blank top panels in overlapped relation over the upper end of the advancing can group during advance thereof, and pressing the paired blank top panels firmly together in adhesively secured relation to complete the can package.

45. The method of enclosing successive can groups within successive wrapper blanks each presenting a bottom panel, a pair of side panels and a pair of top panels which includes, advancing successive flat and unfolded wrapper blanks at uniform speed in a direction parallel to the longitudinal axis of its bottom panel, driving two rows of erected cans diagonally and forwardly in converging relation toward the blank bottom panel advancing therebetween, guiding and pushing the successive leading pair of cans diagonally across the side edges of the adjacent advancing blank bottom panel until fully seated in erect position and in abutting relation on the advancing bottom panel of the flat and unfolded wrapper blanks to thereby provide two rows of bottom panel seated cans longitudinally aligned in the direction of blank travel, separating the end-most pair of cans of the can group prior to their placement on the rear portion of the partly loaded bottom panel from the following pair of cans forming part of the following group to thereby insure deposition of the desired number of paired cans on the loaded bottom panel, upfolding the blank side panels over the sides of the advancing can group, infolding the paired blank top panels in overlapped relation over the upper end of the advancing can group during advance thereof, and pressing the paired blank top panels firmly together in adhesively secured relation to complete the can package.

46. Apparatus for enclosing can groups within one-piece wrapper blanks each presenting a bottom panel, a pair of side panels and a pair of top panel forming sections which includes, a continuously driven conveyor formed by a series of hingedly connected blank supporting platforms, means for feeding successive flat and unfolded wrapper blanks and depositing the bottom panels thereof in supported position on the advancing platforms of the conveyor, a can driving rotor presenting a series of can receiving recesses in the periphery thereof rotatably mounted on one side of the line of travel of said platforms and operative to drive a series of successive erect cans diagonally and forwardly toward the advancing platform supported bottom panels, means for guiding the successively driven cans into erect seated position onto the successively advancing bottom panels of the flat and unfolded wrapper blanks and into an aligned row extending longitudinally in the direction of travel of said conveyor, means for upfolding the side panels of the wrapper blanks around the opposite sides of the successively seated can groups, and means for infolding the paired top panel sections over the upper ends of the successive can groups.

47. Apparatus for enclosing can groups within one-piece wrapper blanks each presenting a bottom panel, a pair of side panels and a pair of top panel forming sections which includes, a continuously driven conveyor formed by a series of hingedly connected blank supporting platforms, means for feeding successive flat and unfolded wrapper blanks and depositing the bottom panels thereof in supported position on the advancing platforms of the conveyor, a can driving rotor presenting a series of can receiving recesses in the periphery thereof rotatably mounted on one side of the line of travel of said platforms and operative to drive a series of successive erect cans diagonally and forwardly toward the advancing platform supported bottom panels, means for guiding the successively driven cans into erect seated position onto the successively advancing bottom panels of the flat and unfolded wrapper blanks and into an aligned row extending longitudinally in the direction of travel of said conveyor, means for upfolding the paired side panels of

the wrapper blanks around the opposite sides of the successively seated can groups, means for infolding the paired top panel sections over the upper ends of the successive can groups, and means for pressing the paired and infolded top panel sections into adhering relation during continuous travel of the blank wrapped can groups.

48. Apparatus for enclosing can groups within one-piece wrapper blanks each presenting a bottom panel, a pair of side panels and a pair of top panel forming sections which includes, a continuously driven conveyor formed by a series of hingedly connected blank supporting platforms, means for feeding successive flat and unfolded wrapper blanks and depositing the bottom panels thereof in supported position on the advancing platforms of the conveyor, a pair of can driving rotors each presenting a series of can receiving recesses in the periphery thereof rotatably mounted on opposite sides of the line of travel of said platforms and operative to drive a twin series of successive erect cans diagonally and forwardly in converging relation toward the platform supported bottom panels advancing therebetween, means for guiding the successively driven cans into paired and erect seated position onto the successively advancing bottom panels of the flat and unfolded wrapper blanks and into twin aligned rows extending longitudinally in the direction of travel of said conveyor, means for upfolding the paired side panels of the wrapper blanks around the opposite sides of the seated can groups, and means for infolding the paired top panel sections over the upper ends of the successive can groups.

49. Apparatus for enclosing can groups within one-piece wrapper blanks each presenting a bottom panel, a pair of side panels and a pair of top panel forming sections which includes, a continuously driven conveyor

formed by a series of hingedly connected blank supporting platforms, means for feeding successive flat and unfolded wrapper blanks and depositing the bottom panels thereof in supported position on the advancing platforms of the conveyor, a pair of can driving rotors each presenting a series of can receiving recesses in the periphery thereof rotatably mounted on opposite sides of the line of travel of said platforms and operative to drive a twin series of successive erect cans diagonally and forwardly in converging relation toward the platform supported bottom panels advancing therebetween, means for guiding the successively driven cans into paired and erect seated position onto the successively advancing bottom panels of the flat and unfolded wrapper blanks and into twin aligned rows extending longitudinally in the direction of travel of said conveyor, means for upfolding the paired side panels of the wrapper blanks around the opposite sides of the seated can groups, means for infolding the paired top panel sections over the upper ends of the successive can groups, and means for pressing the paired and infolded top panel sections into adhering relation during continuous travel of the blank wrapped can groups.
